UNITED STATES PATENT OFFICE.

HUGH D. MACPHERSON, OF SUMMIT, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed August 15, 1921. Serial No. 492,223.

To all whom it may concern:

Be it known that I, HUGH D. MACPHERSON, a citizen of the United States of America, residing at Summit, in the county of Union, State of New Jersey, have invented certain new and useful Improvements in Telephone Systems, of which the following is a full, clear, concise, and exact description.

10 This invention relates to improvements in telephone systems and has particular reference to a system wherein signals for a plurality of toll lines extending between widely separated offices are transmitted over 15 signaling paths common to said toll lines.

In certain systems of the above character it has been customary to provide visual signals for indicating the busy or idle condition of toll lines before an outward operator so that the operator may select an idle line extending to a particular office when initiating a call thereto. It has also been proposed to employ a signaling path common to a plurality of toll lines interconnecting distant offices with means at each end of 25 said path for transmitting thereover supervisory signals characteristic of each individual line and incident to the establishment and release of a connection over said line.

30 In such systems it has been necessary for the outward operator at an initiating office to communicate with the inward operator at a distant or incoming office to verbally inform her of the number of the wanted line whereupon said inward operator proceeds to complete the connection, usually through a toll switching operator.

In other systems means have also been provided for eliminating the necessity of 40 the outward operator communicating the number of the wanted line to the incoming operator by employing a call indicator positioned before the incoming operator and operable, in response to the registration of 45 a call by the outward operator and consequent actuation of signal transmitting means, to indicate the number of the wanted line whereupon the incoming operator may then proceed to complete the connection.

50 When using the call indicator, means have been provided whereby signals individual to each line, which are employed for su-

pervising a connection over said line, and those for controlling the operation of the call indicator, are transmitted over the same 55 signaling path which is common to a plurality of lines.

An object of the present invention is to provide a system wherein a toll switching central office may be joined to a number 60 of distant offices by a plurality of groups of toll lines, each of which is individual to said central office and one of the distant offices, and wherein means are provided for automatically selecting an idle toll line extending to any one of the distant offices and indicating the number of such line before the outward operator at said central office.

Another object is to provide means whereby signals individual to each line of any 70 particular group, which are employed for supervising a connection over said line, and signals for controlling the operation of a call indicator before an incoming operator at the distant office to which said group of 75 lines extends, may be transmitted over separate signaling paths which are common to said group of lines.

Other objects will appear in the course of 80 the following description when taken in connection with the accompanying drawings, Figs. 1 to 16 of which, when arranged in accordance with Fig. 17, illustrate a preferred embodiment of the inventive idea.

General description of operation.

Briefly, the invention contemplates the provision of a plurality of groups of toll lines, each group extending between a central toll switching or outward office and a distant 90 or incoming office. The number of lines in each group may vary in accordance with the volume of traffic between two offices. It has been estimated that, under existing conditions and in view of probable later developments in the use of toll lines, the heaviest traffic between any two offices, such as New York and Philadelphia, may be handled over approximately 400 lines. The present invention has been designed to accomplish the supervision of traffic over a number of groups of toll transmission lines, any one of which groups may contain as many as 400 lines, although it is to be understood

that this number may be increased or decreased in accordance with traffic requirements between two toll centers.

In order that the traffic over the above-mentioned lines may be handled as expeditiously as possible, each originating or outgoing office has a number of outward operator's positions thereat. In accordance with the present invention, these positions are divided into groups and the operator at each position in every group may participate in the establishment of a call between her office and any one of the distant offices connected thereto. To this end, each operator is preferably provided with a number of office keys each of which is individual to one of the distant offices having toll lines terminating in the initiating office. The operation of any one of these keys causes apparatus to function to automatically select an idle toll line of the group individual to the office corresponding to the operated key and to indicate on an indicator, shown in Fig. 16 at the operator's position, the number of the line selected and to be used in completing a call.

Each outward operator is provided with a number of cord circuits, such as indicated at A' (Fig. 2), any one of which may be employed to connect a calling subscriber's line with the selected toll line. At the outward operator's position there is also provided a set of keys operable to register the office, numerical and station designations of a wanted line in the distant office, which office has been selected by the actuation of an office key. The number register keys may be of any preferred type and upon actuation thereof by the outward operator certain relays in the cord register, shown in Fig. 1, corresponding to the operated keys, are energized to prepare circuits for the energization of similar relays in the line register, illustrated in Fig. 6.

After registering the number of the wanted line and receiving the number indication of an idle toll line L, the outward operator then connects the cord circuit A with said idle line, whereupon certain operations take place which result in the connection of the cord and line registers and the energization of relays in the latter in accordance with the condition of relays in the former. The codes for the various office, numerical and station designations of the called line, which consist of impulses of different polarities determined by the condition of the line register relays, are now stored in the line register and await the transmission of supervisory impulses to the distant office which light a guard lamp thereat individual to the toll line taken for use to inform the incoming operator at the distant office that a call is awaiting attention on said line. These supervisory impulses, which are individual

to the line L, are transmitted immediately upon connection of the cord circuit A with the line L and while the line register relays are being operated.

The incoming operator, in response to the actuation of the signal for line L, operates an assignment key which results in the transmission of a code of impulses to the outward office followed by a repetition of this code from the outward office to the inward office to associate the incoming operator's call indicator (Fig. 10) with the line register and a signaling path over which are transmitted all impulses for operating the call indicators at the distance office. Eight series of code impulses are now transmitted in accordance with the condition of the register relays in the line register, these series corresponding to the three office, four numerical and one station designations of the wanted line. In response to these series of impulses the call indicator before the incoming operator is actuated to display, by means of lamps, the number of the called line.

The incoming operator now secures an assignment of a toll switching trunk, such as H, from the toll switching operator and at the same time informs her of the number wanted. The latter operator then connects the toll switching trunk with the called subscriber's line. The incoming operator connects the line L with the toll switching trunk which results in the release of the call indicator and the transmission of the individual code of line L to the outward office to light a guard lamp thereat and in response thereto the outward operator actuates the ringing key to signal the wanted subscriber. When the call is answered a code of impulses is again transmitted to the outward office to extinguish the guard lamp after which the outward operator no longer actuates the ringing key.

At the termination of a conversation the release of the connection is effected by the called subscriber replacing his receiver upon its switch hook, whereupon a code of impulses is transmitted to the outward office to again light the guard lamp to give the outward operator the disconnect signal. This operator then disconnects the cord circuit A from the toll line L which causes the transmission of a code of impulses to the inward office to simultaneously light the guard lamps before the incoming and toll switching operators, who then restore the circuit to normal by disconnecting the line L from the trunk H and said trunk from the called subscriber's substation circuit, respectively.

At any time during the conversation the called subscriber may recall the outward operator by moving the switch hook up and down. Codes of impulses are transmitted

from the inward to the outward office and their reception at the latter office causes apparatus to function to flash the guard lamp before the outward operator, who thereupon connects her head set to the line.

If at the time of establishing a call the toll switching operator finds the wanted line busy, she inserts the plug of trunk H into a busy flash jack. This operation causes the guard lamp before the outward operator to flash and upon connecting her head set to the line she receives a distinctive tone indicating a busy condition on the line wanted. The release of the connection is then effected as previously referred to.

The operation of automatically selecting a toll line in the desired group and indicating the number of such line before the outward operator is illustrated in Figs. 12 to 16 inclusive of the drawings. In Fig. 16, three outward operators' positions of a group, which usually contains twenty positions, are indicated, the toll line number indicator for the third position being shown in detail. As illustrated, these three positions are located in the third group of operators of which there may be five, although the apparatus for only three groups has been shown. A set of sequence relays, generally indicated at B (Fig. 15) and common to the third group of operators' positions, is provided, and upon the operation of a pair of relays individual to any position of the group at which an office key has been actuated, said sequence relays become effective to prevent any of the other operators at the remaining positions of the group from securing an assignment of an idle toll line until the position of the first operator to initiate a call has been found by a position-finding switch. A second set of sequence relays, generally indicated at C and containing as many pairs of relays as there are groups of operators' positions, is common to all of said groups of operators' positions and is effective, when an operator in any group initiates a call to a certain distant office, to bar all other operators of all other groups from receiving an assignment of an idle toll line extending to said certain office until an operator-position-finding switch has located the calling operator's position. Operators in other groups may, however, secure an assignment of an idle line extending to a different distant office while the said calling operator's position is being sought.

A plurality of links are provided for each group of toll lines extending between an outward and an incoming office. Only three of these links and associated apparatus have been indicated but it will be understood that this number may be varied in accordance with traffic conditions. In the illustration these links have been assumed to be assigned to the toll lines leading to Philadelphia, the

four conductors for the first and second links and their associated apparatus being shown in Figs. 14 and 13 respectively, while the four conductors for the third link, the apparatus of which is indicated by the rectangle D, are shown in Fig. 13. A rotary switch E is designed to preselect an idle one of these links so that when a call is initiated to Philadelphia by an outward operator in any group, the set of sequence relays C, common to said groups, is immediately connected with the apparatus associated with the preselected link. This apparatus consists, in each instance, of a plurality of operator-position-finding switches, those for the first link being indicated at F¹, F² and F³; and those for the second link at G¹, G² and G³. The switches F¹ and G¹ of the first and second links and all other corresponding switches of the other links are individual to the first group of operators; the switches F², G², etc., to the second group of operators, and the switches F³, G³, etc., to the third group of operators. These various switches, when operated, function to find a calling operator's position in the group to which each is individual. Thus, in the case assumed and illustrated, when the operator at the third position in the third group actuates the Philadelphia office key, the third pair of sequence relays, counting from the left, of the set C is operated and, in a manner later to be described in detail, causes the switch G³ of the second Philadelphia link which link has been preselected by the switch E, to hunt over its terminals until those individual to the third position of the third group of operators' positions are encountered, whereupon switch G³ comes to rest. The operation of switch G³ initiates the selection of an idle toll line by one of a plurality of switches, two of which are designated by K and K¹ and shown in Fig. 12. Each of these switches is designed to hunt over the terminals of twenty toll lines so that with 400 lines extended between an outward and inward office it will be necessary to provide twenty of these switches for each link. If the first switch K does not find an idle line, the second switch K¹ will then be caused to hunt. If it fails to find an idle line the third switch (not shown) will be started, and so on until an idle line is located. The switch finding the idle line is then associated with a number indicator controlling mechanism, shown at the right of the dotted line in Fig. 12, which operates in conjunction with said switch and through wipers of the switch G³ to cause the operation of the number indicator (Fig. 16) whereby certain lamps therein are lighted to indicate the number of line selected. After the outward operator has inserted the plug of a cord circuit, such as A, into the jack of the selected toll line, the apparatus for se-

lecting and indicating this line is restored to normal so that the same may be employed for other selections and indications.

With this brief description of the invention in mind it is believed that the invention will now be fully understood from the following detailed description of the operation.

Outward operator registers number of called line in cord circuit register.

10 A calling subscriber may be connected to the outgoing operator in any manner well known in the art. Since this operation forms no part of the present invention the 15 apparatus for making this connection is not shown in its entirety, only a portion of the outgoing operator's cord circuit A, which is employed to connect to the calling subscriber's line, being illustrated.

20 Upon ascertaining the number of the called subscriber's line in Philadelphia from the calling subscriber, the outgoing operator first proceeds to set up this number on the cord circuit register illustrated in Figs. 1 25 and 2. It will be assumed that the office designation of the wanted line is represented by the letters WAL and the station designation of said line by the letter M. The register relays are arranged in groups and 30 those for the office designations are indicated by the numerals 114 to 125, while relays for station designations are indicated by the numerals 126 to 129. The relays of the register representing the number digits 35 of called lines have been omitted for purposes of economy in space and description, but it will be understood that these number relays operate in the same manner as the office and station relays. The operator 40 first depresses the key 9, which corresponds to the first letter of the office designation, whereupon an operating circuit is established for register relay 116 of the first group, which circuit extends from ground, 45 through the winding of relay 100, the right-hand alternate contact of key 9, the right-hand normal contact of key 6, the left-hand normal contact key 5, the lower normal contact of the transfer relay 102 individual to 50 the first group of register relays, and the lower winding of relay 116 to grounded battery. An operating circuit is also established for relay 117 of the first group, which 55 circuit extends from ground, through the winding of relay 100, left-hand alternate contact of key 9, the upper normal contact of relay 102, and the lower winding of relay 117 to grounded battery. Relay 100 is also energized in either of these circuits, and in 60 closing its contact establishes a circuit for relay 103 extending from grounded battery through the winding of said relay, the lower normal contact of relay 101, and thence to ground through the contact of relay 100.

Relay 103 energizes to close a circuit through 65 its contact, the windings of relays 102 and 101 in series, and the contact of relay 113 to ground. Relays 101 and 102 do not energize in this circuit since they are short-circuited by the ground connected to contact 70 of relay 100, and extending through the lower normal contact of relay 101, and contact of relay 103. Relays 116 and 117, upon energization, are locked up through their upper windings and contacts to ground at 75 the contact of relay 113. The operator now releases the key 9, whereupon relay 100 releases to remove the short-circuit from the windings of relays 101 and 102, and these relays thereupon energize over the circuit 80 extending to ground at the relay 113 to transfer the conductors extending from the various keys of the operator's set to the normal contacts of the second group of transfer relays 104 and 105. The operator 85 next depresses key 2 and again establishes a circuit for relay 100 and register relay 119 of the second group, said circuit extending from ground, through the winding of relay 100, the left-hand alternate contact of key 2, 90 the lower alternate contact of relay 101, the middle normal contact of relay 104 and the lower winding of relay 119 to grounded battery. Relays 100 and 119 energize, and the latter relay locks through its upper winding 95 and contact to ground at the contact of relay 113. The energization of relay 100 now establishes a circuit for relay 106, extending from grounded battery, through the winding of said relay 106, the lower normal contact 100 of relay 104, the upper contact of relay 102, and the contact of relay 100 to ground. Relay 106 energizes, and through its contact 105 closes a circuit in series, through the windings of relays 104 and 105 to ground at the contact of relay 113, but, as before described in connection with relays 101 and 102, relays 104 and 105 are short-circuited as long as relay 100 remains operated. Upon the release of key 2, relay 100 releases to remove 110 this short-circuit, and relays 104 and 105 thereupon energize. Relay 106 locks up in the circuit described for relays 104 and 105. The conductors leading from the keyboard 115 are now extended through the alternate contacts of transfer relays 101, 102 and 104, 105 to the normal contacts of relays 107 and 108. Upon the depression of the key 5, corresponding to the third letter of the office designation, relays 100 and 124 are operated over a circuit extending from ground, through the winding of relay 100, the left-hand alternate contact of key 5, the lower alternate contacts of relays 102 and 105, the lower normal contact of relay 108 and the lower winding of relay 124 to battery. Relays 100 and 124 energize, and the latter 125 relay locks through its upper contact to

ground at the contact of relay 113. The energization of relay 100 establishes a circuit for relay 109 extending from grounded battery through the winding of relay 109, 5 the lower normal contact of relay 107, the upper contacts of relays 105 and 102, and the contact of relay 100 to ground. The energization of relay 109 establishes a circuit for relays 108 and 107 in series to 10 ground at the contact of relay 113, but said relays 108 and 107, as before described in connection with the other transfer relays, are short-circuited until relay 100 releases, whereupon said relays energize in the locking 15 circuit for relay 109. The setting up of the office designation is now completed, and the operator then proceeds to depress keys corresponding to the number digits of the called line. In response to the successive 20 actuation of these keys, the number register relays and corresponding transfer relays, which have been omitted from the drawing, are operated in the same manner as described for the office register relays. The 25 operator then completes the registration of the called line by actuating the key 6, which corresponds to the station designation of said line, whereupon relays 100, 126 and 128 will operate over circuits which will be 30 obvious from an understanding of the description of operation of the other register relays. Relay 112 also energizes upon the operation of relay 100 over a circuit extending through the lower normal contact 35 of relay 110 and the upper contacts of relays 108, 105 and 102. When relay 100 releases in response to the restoration of the key 6, relays 110 and 111 are energized in series with relay 112. The operation of 40 transfer relay 111 connects battery through its upper contact to the winding of relay 200, but this relay does not energize until the line register (Fig. 6) and apparatus associated with the toll line are in condition 45 to receive impulses from the cord register, which occurs after the plug 203 of the cord circuit A is inserted into the jack 300 of the idle toll line L, as will be more fully described hereinafter. Register relays corresponding to digits in the wanted line are 50 now operated and locked, and transfer relays individual to the groups of register relays are also energized.

55 Should the operator at any time desire to erase the registration made, she may do so by actuating the wipe-out key 130, which closes an obvious circuit for relay 113. The operation of this relay removes ground from the contact thereof, and thus opens the holding circuits for such transfer relays as have been operated and the locking circuits of the register relays and of relays individual to said transfer relays. The apparatus is thereby restored to normal, and the opera-

tor may then proceed to again register the 65 called number.

Outward operator actuates Philadelphia office key.

Having recorded the number of the wanted line in the cord register the operator now actuates the Philadelphia office key 1500, whereupon an obvious circuit is established to operate relay 1501 which locks through its right-hand contact to ground at the contact of slow-to-release wipe-out relay 1502 of a mechanism which is individual to the operator's position, there being a similar mechanism associated with each of the other office keys. The actuation of the key 1500 also establishes a circuit for relay 1504 extending from grounded battery through the winding of said relay, the normal contact of relay 1506 and the right-hand contact of key 1500 to ground. Relay 1504 energizes and locks through its contact, the winding of relay 1506 and the contact of relay 1502 to ground. This locking circuit extending through the winding of relay 1506 has no effect at this time upon this relay since the same is short-circuited by the ground extending from the right-hand contact of key 1500, the normal contact of relay 1506 and the contact of relay 1504. As soon as the operator releases key 1500 this ground, which short-circuits the relay 1506, is removed and said relay energizes in series with the locking circuit for relay 1504. When relay 1501 energizes an operating circuit for relay 1507 is established extending from grounded battery through the winding of relay 1507, the left-hand contact of relay 1501 and the contact of relay 1502 to ground. The operation of relay 1507 disconnects ground from a terminal of switch G³ over which the wiper 1300 thereof passes and which is individual to the third operator's position. The energization of relay 1501 also establishes a circuit for the relay 1513 individual to the third operator's position, said circuit being traceable from grounded battery through the normal contact of relay 1516, the winding of relay 1513, the normal contact of relay 1503, the right-hand contacts of relay 1501 and the contact of relay 1502 to ground. Relay 1513 energizes in this circuit to establish an operating circuit for slow-to-release relay 1514 extending from grounded battery through the winding of relay 1514, the alternate contact of relay 1513 and the normal contacts of relays 1511 and 1509 to ground. The energization of relay 1514 loses a circuit to operate relay 1517 which extends from grounded battery through the winding of relay 1517, the left-hand normal contacts of relays 1510 and 1512 in series, and the alternate contact of relay 1514, and

thence over the energizing circuit for the latter relay. As long as relays 1513 and 1514 are operated, which condition exists until the third position has been selected by the position finding switch G^3 , as will later appear, all other operators in the same group are prevented from actuating their individual sequence relays to secure an assignment of a toll line extending to Philadelphia. Operators at the preceding positions, such as positions 1 and 2, are thus prevented due to the fact that neither of the relays 1509 and 1511 can be energized since the circuits therefor extend through the right-hand normal contact of relay 1514. Operators at succeeding positions may energize relays, such as relay 1515, but associated relays, such as relay 1516, will not be operated since the circuits for the latter relays extend through the normal contact of relay 1513.

The operation of relay 1517, which is common to the third group of operators' positions, establishes an obvious operating circuit for the relay 1522 which, together with relay 1523, is individual to the third group of operators. When relay 1522 energizes a circuit is established to energize relay 1523, said circuit being traceable from relay 1523, the alternate contact of relay 1522 and the normal contacts of relays 1520 and 1518 to ground. During the operation of relays 1522 and 1523, which remain operated as long as relay 1517 is energized, operators of the remaining groups are prevented from securing an assignment of an idle toll line to Philadelphia. If operators at any preceding groups should depress the Philadelphia office key at their positions a relay, similar to relay 1517, will be energized, but neither of the relays 1518 or 1520 can be operated inasmuch as the circuit for these relays extends through the normal contact of relay 1523. Operators of groups succeeding group 3 likewise cannot secure an assignment of an idle toll line since circuits for relays individual to said succeeding groups and similar to relay 1523 cannot be established since said circuits must extend through the normal contact of relay 1522.

In order that contemporaneous calls to Philadelphia may be evenly distributed amongst the various groups of operators and the operators' positions of each group in the order of their number, a circuit is so arranged that, for instance, when the third position of the third group has been found by the group hunting switching G^3 and relay 1514 is released in consequence thereof to open the energizing circuit for relay 1517, another operator in group 3 will be unable to secure an assignment of a toll line if there are operators in other groups awaiting an

assignment. Thus, when relay 1514 releases and closes its right-hand normal contact, a circuit may be established for relays, such as relays 1509 and 1511, but before either of the relays 1510 or 1512 can energize to 70 again establish a circuit for relay 1517, a relay, similar to the latter and common to some other group of operators' positions, which is already operated, will cause the energization of a relay, similar to relays 1518, 75 or 1520, in which case relay 1523, individual to the third group, cannot again be operated. The calling operator in the third group must, therefore, await the assignment of a toll line to some operator in one of the other groups. If operators in the first and second groups are calling contemporaneously and the relays, similar to relay 1517 and individual to said groups, are both energized at the same time, the operator in the first group is 80 given preference although both relays 1518 and 1520 may be energized simultaneously. This is due to the fact that with the energization of relay 1518 the circuit for relay 1521 is opened at the normal contact of relay 1518 before the alternate contact of relay 1520 can be closed. 85

Returning to the operation of relays 1522 and 1523 at the time relay 1517 is energized, it will be seen that the operation of the former relays connects ground to the wiper 1526 of the allotter switch E through the normal contacts of relays 1518 and 1520 in series and the alternate contacts of relays 1522 and 1523. The allotter E has previously preselected the second Philadelphia link circuit and with the wipers of switch E resting upon the associated third contacts, the first contacts being vacant, the ground on the wiper 1526 is extended through the wiper 1300 of switch G^3 in its normal position, the normal contact of relay 1306 and the contact and winding of the stepping magnet 1307 of switch G^3 to grounded battery. This circuit also extends through the winding of relay 1306 but said relay is normally shunted by wiper 1300. Stepping relay 1307 operates to step wipers 1300 to 1305 of switch G^3 from their normal positions in search of terminals individual to the third operator's position in the third group. When the wiper 1300 engages the second terminal in its associated row, a circuit is again established for stepping magnet 1307 extending from grounded battery through the winding and contact of said magnet, the normal contact of relay 1306, wiper 1300 and the second terminal engaged thereby, and from thence to ground at the normal contact of a relay at the first operator's position 110 similar to relay 1507. The stepping magnet again steps the wipers of switch G^3 to the third set of terminals and a circuit is again closed for magnet 1307 through the wiper 1300 to ground at the relay of the second op- 115

120

130

erator's position similar to relay 1507. The wipers of switch G^3 are again stepped and this time are engaged with the fourth set of terminals which are individual to the third operator's position. The relay 1507 of this position being energized, the ground is removed from the terminal engaged by wiper 1300 and a short-circuit for relay 1306 will no longer exist. This relay, therefore, energizes in series with stepping magnet 1307, in which case said magnet will no longer operate and the brushes of the switch will be brought to rest upon the terminals individual to the third operator's position in the third group. The operation of relay 1306 closes a circuit extending from ground through the left-hand alternate contact of said relay, the wiper 1300 and terminal engaged thereby, the alternate contact of relay 1507, the normal left hand contact and armature of relay 1505, through the winding of relay 1503 to grounded battery. Relay 1503 energizes and locks through its alternate contact, the winding of relay 1505 and the contact of relay 1502 to ground. This circuit, through the winding of relay 1505, fails to energize this relay since the same is short-circuited by ground at relay 1306 extending through the alternate contact of relay 1503. The operation of relay 1503 opens, at its normal contact, the holding circuit for relay 1513, which thereupon releases and in turn releasing relays 1514 and 1517. The operation of relay 1306 also establishes an energizing circuit for relay 1308 extending from grounded battery through the winding of relay 1308, the right-hand contacts of relay 1306, wiper 1301 and terminal engaged thereby, the alternate contact of relay 1507, wiper 1300 and terminal engaged thereby, and the left-hand alternate contact of relay 1306 to ground. The operation of relay 1308 in this circuit establishes a self-interrupting circuit for the magnet 1524 of the allotter switch E , said circuit extending from grounded battery through the winding and contact of magnet 1524, wiper 1525, the right-hand contacts of relay 1308, and from thence to ground at the normal contact of relay 1309, which is common to all of the position-finding switches associated with the second link. The closure of this circuit causes magnet 1524 to step the wipers of switch E to the next set of contacts which are individual to the third Philadelphia link circuit. If a relay similar to relay 1308 of any of the position-finding switches associated with the third link is energized and ground is connected to the terminal engaged by wiper 1525, said ground extending from the normal contact of a relay of the third link similar to relay 1309 and through the right-hand contacts of a relay of a position hunting switch of the third link similar to relay 1308. This ground denotes a busy

condition of the link and causes the wipers of the allotter E to be stepped to the next succeeding terminals. This operation continues until the wiper 1525 engages a terminal free from ground whereupon the allotter switch comes to rest and thus pre-selects an idle Philadelphia link. With another link now selected and the relays 1513 and 1514 restored to normal, it is apparent that another operator in the third group, or operators in other groups, depending upon the condition of the sets of sequence relays B and C , may secure an assignment of an idle toll line.

Selection of an idle toll line to Philadelphia. 80

Having thus selected the third operator's position in the third group, the switch G^3 , through the medium of the operation of relay 1308 thereof, causes the selection of 85 an idle toll line by one of the switches K , K^1 , etc., which are individual to the second link with which switch G^3 is associated. The operation of relay 1308 closes a circuit extending from ground through the left-hand contact of said relay, the common conductor 1310, the winding of relay 1200 and the contact of stepping magnet 1201 of switch M to grounded battery. Relay 1200 energizes in this circuit to close an operating circuit 90 for relay 1202 extending from grounded battery through the winding and continuity contacts of said relay and the contact of relay 1200 to ground. Relay 1202, in operating, closes a locking circuit for itself extending through the left-hand alternate contact of said relay, and from thence over the conductor 1310 to ground at the left-hand contact of relay 1308. The switch M , which forms a part of the number indicating mechanism shown at the right of the dotted line in Fig. 12, comprises six wipers 1203 to 1208, the first three of these wipers being employed to determine the hundreds digit of the idle trunk which is selected by one of the switches K , K^1 , as will more clearly appear in the course of the description. With the wipers of switch M in their normal positions the energization of relay 1200 also establishes a circuit extending from ground through the contact of relay 1200, the wiper 1208 and terminal engaged thereby, the wiper 1209 of the switch K , the normal contact of relay 1210 of said switch and the contact and winding of stepping magnet 1211 to grounded battery. This stepping circuit also extends through the winding of relay 1210 but this relay is short-circuited through its normal contact. The closure of the stepping circuit for magnet 1211 causes said magnet to step its wipers from their normal positions. The terminals over which wiper 1209 moves are the test terminals of the toll lines served by said switch, these terminals being also multiplied to similar terminals of 100 105 110 115 120

switches corresponding to switch K and associated with other link circuits. The busy condition of a toll line is denoted by ground connected to the terminal individual to said line at relay 302 by the operation of the line circuit relay 301 thereto. Thus, each time wiper 1209 engages a terminal to which ground is connected, this ground will be extended through said wiper and the normal contact of relay 1210 to energize the stepping magnet 1211, which will then step the wipers of switch K to the next succeeding terminals. As previously referred to, each of the switches K, K¹, etc. have twenty trunks assigned thereto, and should all the twenty trunks served by switch K be busy, said switch will take twenty steps whereupon the wiper 1209 will engage the next to the last terminal of its associated row. The brush 1209, not finding ground at this point, removes the short-circuit from the winding of relay 1210 which thereupon energizes in series with the magnet 1211, but the said magnet will not operate in this series circuit and the switch is, therefore, brought to rest. The energization of relay 1210 establishes a circuit for the differential relay 1212 extending from grounded battery through the left-hand high resistance winding of relay 1212, the wiper 1209 and contact engaged thereby, and the inner alternate contact of relay 1210 to ground. Relay 1212 operates in this circuit to establish an obvious energizing circuit for slow-to-release relay 1213. The operation of relay 1210 also closes a circuit extending from grounded battery through the winding of relay 1214, the inner normal contact of relay 1212 before said contact is opened, and the right-hand alternate contact of relay 1210 to ground. The circuits for relays 1212 and 1214 are established simultaneously and hence the relay 1214 will not get sufficient current to fully energize the same before the inner normal contact of relay 1212 is opened. If it should happen that relay 1214 did close its contact, no effect would be produced thereby inasmuch as the outer normal contact of relay 1212 would be opened before the outer alternate contact of relay 1214 was closed. The operation of relay 1213, in response to the energization of relay 1212, connects ground through its outer contact to the low resistance right-hand winding of relay 1212, but this winding is at this time shunted by ground at the inner alternate contact of relay 1210 and, therefore, relay 1212 will remain energized. The operation of relay 1213 also closes a circuit extending from grounded battery through the inner contact of relay 1213, the outer right-hand alternate contact of relay 1202, the winding of the stepping magnet 1201, and the inner right-hand alternate contact of relay 1202 to ground. The closure of this circuit energizes the magnet 1201, but the energization of said magnet has no effect upon the wipers of switch M since the escape mechanism controlled by magnet 1201 is so arranged that said wipers will be stepped upon the release of said magnet. The energization of magnet 1201 opens the circuit for relay 1200 by disconnecting battery therefrom, and this relay thereupon releases. The deenergization of relay 1200 removes ground from the winding of relay 1210, and this relay thereupon releases to remove the short-circuit from the low resistance winding of relay 1212. This low resistance winding is then connected in series with the high resistance winding of relay 1212, whereupon this relay releases to open the energizing circuit for relay 1213 which, after an interval, opens its contacts. After the release of relay 1210 but before relay 1213 can open its contacts, a circuit is established for stepping magnet 1211 extending from grounded battery through the winding and contact of said magnet, the normal contact of relay 1210, wiper 1209 and the terminal engaged thereby, the low resistance winding of relay 1212 and the right-hand contact of relay 1213 to ground. Magnet 1211 is operated in this circuit to step the wipers of switch K to their normal positions. When relay 1213 opens its contacts battery is disconnected from the winding of the stepping magnet 1201, which thereupon releases to step the wipers of switch M to the next succeeding terminals. The release of magnet 1201 again connects battery to the winding of relay 1200 which again operates to connect ground to the wiper 1208 in its second position, and from thence through the wiper 1217 of switch K¹ and the normal terminal engaged by said wiper, the normal contact of relay 1221 and the contact and winding of magnet 1222 to grounded battery. Magnet 1222 operates the wipers of switch K¹ in the same manner that the wipers of switch K were operated, and wiper 1217 of switch K¹ tests for ground on the terminals over which it passes in search of an idle toll line, the terminals associated with the wiper 1217 being also multiplied to the terminals of switches similar to switch K¹ associated with the other links. During the operation of the stepping magnet 1222, relay 1221 is short-circuited through its normal contact and will not operate until the wiper 1217 encounters the terminal of an idle line. Under the assumption that line L shown in Fig. 3 is the first idle line encountered by the wiper 1217 it will be seen that when said wiper engages the terminal connected to the conductor leading to a contact of relay 302 ground will no longer be found and the relay 1221 will operate in series with the stepping magnet 1222 in which case the magnet no longer operates and the wipers of

switch K¹ are brought to rest upon terminals individual to the line selected.

Before proceeding further with the description of operation it is believed that an explanation of the purpose of the wipers 1216, 1218, 1219, 1220 of switch K¹ and corresponding wipers of other similar switches will aid in better understanding the invention. When an idle line has been found by one of the switches, which are all similar to each other, the wipers corresponding to wipers 1218, 1219 and 1220 of said switch are designed to control the operation of one or more of the units relays 1602 to 1605 of the number indicator. The rows of terminals passed over by each of said wipers are divided into two groups, there being ten terminals in each group, one for each of the units digits 0 to 9. In every instance, the terminals of the upper group of each row are arranged and connected in the same manner as those in the lower group in said row so that whether the wiper associated with said row is in engagement with the terminal in the lower group or the corresponding terminal of the upper group, the same potential will be connected to said wiper. In order that the units relays 1602 to 1605 may be properly controlled, the various terminals of the rows associated with wipers 1218, 1219 and 1220 have either no potential, a low resistance ground or a high resistance ground connected thereto. For example, in the row of terminals passed over by the wiper 1218, the second and twelfth terminals which represent the units digit 0 in both the lower and upper groups, have no potential connected thereto. Again, in the row passed over by the wiper 1219, the fourth and fourteenth terminals which are individual to the units digit 2 are connected to a low resistance ground. Likewise, in the row associated with wiper 1220, the fifth and fifteenth terminals which represent the digit 3 are connected to ground through a resistance 1223. Therefore, with the wipers 1218, 1219 and 1220 resting on corresponding terminals in their associated rows, the potentials existing on said terminals are transmitted through a train of relays, generally indicated at N and forming a part of the number indicator controlling mechanism, and through wipers of switch G⁸ to control the units relays of the number indicator.

With respect to the wiper 1216 and other corresponding wipers, the rows of terminals associated therewith are also divided into two groups. These wipers are designed to control the operation of one or more of the tens relays 1224 to 1227 inclusive of the number indicator controlling mechanism, which, in turn, control, through the relays N, the tens relays 1608 to 1611 inclusive of the number indicator. The lower group of terminals over which the wiper of switch

K, corresponding to wiper 1216 passes, is not connected to any of the tens relays and is employed to designate the tens digit 0. The upper group of terminals passed over by said wiper is assigned to the tens digit 1. The lower group of terminals associated with wiper 1216 of switch K¹ is individual to the tens digit 2 while the upper group is individual to the tens digit 3. In the third switch (not shown) the lower and upper groups over which a wiper similar to wiper 1216 passes are assigned, respectively, to the tens digits 4 and 5. There being five switches similar to switch K for each one hundred toll lines, it will be apparent that each of the remaining tens digits will be represented in the rows of terminals associated with the wipers similar to wiper 1216 of the two other switches for the first one hundred lines. Since there are four hundred lines, it will be obvious that each tens digit will be represented four times and therefore the groups of terminals assigned to the digits 1 to 9 in the switches associated with the remaining three hundred lines are multiplied to the conductors 1228, 1229 and 1230. Inasmuch as the four groups of terminals assigned to the digit 0 are not connected to any of the tens relays 1224 to 1227, these groups need not be multiplied.

As previously mentioned, the set of hundreds relays 1614 to 1618, inclusive of the number indicator are controlled through wipers 1203, 1204, and 1205 of the switch M. Thus, when a line in the first hundred is selected by one of the first five switches K, each of the wipers 1203, 1204 and 1205 will be connected to one of the first five terminals in its associated row. There being no potential connected to any of these terminals, one of the hundreds relays of the number indicator will be operated and therefore the lamp 0 will light, as will later appear. If a line in the second hundred is selected, the wipers 1203, 1204 and 1205 will be resting upon one of the next five terminals of their associated rows. The low resistance ground will then be connected to the wiper 1203 and no potential to wipers 1204 and 1205. This will result in the energization of relay 1614 and subsequent lighting of lamp 1. If the line selected is in the third hundred, wiper 1204 will be connected to the low resistance ground while the other two wipers, 1203, and 1205, will have no potential connected thereto. This condition will result in the lighting of the hundreds lamp 2. If the selected line is in the fourth hundred, ground through resistance 1231 will be connected to wiper 1205 to energize relay 1617 and light the hundreds lamp 3. The other hundreds lamps and the circuits therefore, which are not used where only four hundred lines are employed, are shown to illustrate the adaptation of the number in-

dicator to systems wherein more lines may be employed.

Operation of the toll line number indicator and its controlling mechanism.

5. Proceeding now with the description of the operation, it will be recalled that the switch K¹ has selected an idle toll line and that relay 1221 of said switch has been operated.
10. The energization of relay 1221 closes a circuit for the differential relay 1232 extending from grounded battery through the right-hand high resistance winding of said relay, wiper 1217 and terminal engaged thereby and the inner alternate contact of relay 1221 to ground. Relay 1232 operates in this circuit to close an obvious operating circuit for slow-release relay 1233 which, in energizing, connects ground to the low resistance left-hand winding of relay 1232 but this winding is, at this time, short-circuited by the ground at the left-hand alternate contact of relay 1221 and hence relay 1232 will remain operated. The operation of relay 1221 also establishes an energizing circuit for relay 1234 extending from grounded battery through the winding of relay 1234, the inner right-hand contact of the differential relay 1235 and the outer contacts of relay 1221 to ground.
15. The differential relay 1235 is similar to the previously described relay 1212 of the switch K which was operated after the wipers of switch K had passed over all of the toll line terminals of their associated rows. Relay 1235, however, is not operated at this time since the wiper 1217 is not in engagement with the next to the last terminal of its row. It will be noted that the wipers of switch K¹ are in engagement with terminals of the upper groups. In accordance with the previous description the upper group of terminals associated with wiper 1216 is individual to the tens digit 3. Therefore, upon the energization of relay 1234, a circuit is established extending from ground through the inner contact of relay 1234, the wiper 1216 and terminal engaged thereby, conductor 1230 and the right-hand winding of the tens relay 1226 to grounded battery. This relay operates to prepare a circuit including contacts of certain of the N relays and a wiper of switch G³ for operating the tens relay 1610 which, upon its energization, prepares a circuit to light the tens lamp 3 as will appear in the course of the description.
20. The circuit for energizing the tens relay 1610 and also the circuits controlled by the position of wipers 1218, 1219 and 1220 for energizing one or more of the units relays now awaits the operation of the train of relays N. This operation is initiated by the energization of relay 1234 which establishes a circuit for relay 1236 extending from grounded battery through the winding of said relay, the outer contact of relay 1234 and the outer normal contact of relay 1235 to ground. The operation of relay 1236 in this circuit connects the interrupter 1237 through the upper contact of relay 1236, the 70 normal contact of relay 1238 and the winding of relay 1239 to grounded battery. When the brush of the interrupter is in engagement with a grounded segment, ground is extended over the path just traced to 75 energize the relay 1239. This relay operates and locks through its winding and contact and the winding of relay 1238 to ground at the lower contact of relay 1236. This locking circuit extending through the winding 80 of relay 1238 does not energize the latter relay since the same is short-circuited through its normal contact and the contact of relay 1239 as long as the brush of interrupter 1237 is in engagement with a 85 grounded segment. When an ungrounded segment of the interrupter is reached the short circuit from the relay 1238 is removed and this relay energizes in series with the locking circuit of relay 1239. Upon next 90 reaching a grounded segment the interrupter 1237 establishes a circuit extending from ground through the upper contact of relay 1236, the alternate contact of relay 1238, the upper normal contact of relay 95 1240 and the windings of relays 1241 and 1242 in series to grounded battery. Relays 1241 and 1242 energize in this circuit and lock through their windings and lower contacts of relay 1241 the winding of relay 1240 100 to ground at the lower contact of relay 1236. Relay 1240 does not energize in this circuit until the short circuit therefor extending through the contacts of relays 1236, 1238, 1240 and 1241 is removed by the engagement of the brush of relay 1237 with an ungrounded segment. Upon next engaging a grounded segment, the brush of the interrupter 1237 closes a circuit for relays 1243 and 1244 extending from grounded battery 105 through windings of these relays in series, the upper normal contact of relay 1245, the alternate contacts of relays 1240 and 1238, the upper contact of relay 1236 to the ground through the interrupter 1237. Relays 1243 and 1244 energize and lock through their windings and lower alternate contact of relay 1244, winding of relay 1245 and lower contact of relay 1236. The relay 1245 is short-circuited in the same manner that relays 1238 and 1240 were short-circuited and does not operate until the brush of interrupter 1237 engages an ungrounded segment. The next engagement of the brush 115 of interrupter 1237 with a grounded segment closes a circuit to operate relays 1246 and 1247, said circuit being traceable from grounded battery through the windings of these relays in series, the upper contact of relay 1248, the alternate contacts of relays 120 125 1249 and 1250, the upper contact of relay 1251, the alternate contacts of relays 1252 and 1253, the upper contact of relay 1254, the alternate contacts of relays 1255 and 1256, the upper contact of relay 1257, the alternate contacts of relays 1258 and 1259, the upper contact of relay 1260, the alternate contacts of relays 1261 and 1262, the upper contact of relay 1263, the alternate contacts of relays 1264 and 1265, the upper contact of relay 1266, the alternate contacts of relays 1267 and 1268, the upper contact of relay 1269, the alternate contacts of relays 1270 and 1271, the upper contact of relay 1272, the alternate contacts of relays 1273 and 1274, the upper contact of relay 1275, the alternate contacts of relays 1276 and 1277, the upper contact of relay 1278, the alternate contacts of relays 1279 and 1280, the upper contact of relay 1281, the alternate contacts of relays 1282 and 1283, the upper contact of relay 1284, the alternate contacts of relays 1285 and 1286, the upper contact of relay 1287, the alternate contacts of relays 1288 and 1289, the upper contact of relay 1290, the alternate contacts of relays 1291 and 1292, the upper contact of relay 1293, the alternate contacts of relays 1294 and 1295, the upper contact of relay 1296, the alternate contacts of relays 1297 and 1298, the upper contact of relay 1299, the alternate contacts of relays 1300 and 1301, the upper contact of relay 1302, the alternate contacts of relays 1303 and 1304, the upper contact of relay 1305, the alternate contacts of relays 1306 and 1307, the upper contact of relay 1308, the alternate contacts of relays 1309 and 1310, the upper contact of relay 1311, the alternate contacts of relays 1312 and 1313, the upper contact of relay 1314, the alternate contacts of relays 1315 and 1316, the upper contact of relay 1317, the alternate contacts of relays 1318 and 1319, the upper contact of relay 1320, the alternate contacts of relays 1321 and 1322, the upper contact of relay 1323, the alternate contacts of relays 1324 and 1325, the upper contact of relay 1326, the alternate contacts of relays 1327 and 1328, the upper contact of relay 1329, the alternate contacts of relays 1330 and 1331, the upper contact of relay 1332, the alternate contacts of relays 1333 and 1334, the upper contact of relay 1335, the alternate contacts of relays 1336 and 1337, the upper contact of relay 1338, the alternate contacts of relays 1339 and 1340, the upper contact of relay 1341, the alternate contacts of relays 1342 and 1343, the upper contact of relay 1344, the alternate contacts of relays 1345 and 1346, the upper contact of relay 1347, the alternate contacts of relays 1348 and 1349, the upper contact of relay 1350, the alternate contacts of relays 1351 and 1352, the upper contact of relay 1353, the alternate contacts of relays 1354 and 1355, the upper contact of relay 1356, the alternate contacts of relays 1357 and 1358, the upper contact of relay 1359, the alternate contacts of relays 1360 and 1361, the upper contact of relay 1362, the alternate contacts of relays 1363 and 1364, the upper contact of relay 1365, the alternate contacts of relays 1366 and 1367, the upper contact of relay 1368, the alternate contacts of relays 1369 and 1370, the upper contact of relay 1371, the alternate contacts of relays 1372 and 1373, the upper contact of relay 1374, the alternate contacts of relays 1375 and 1376, the upper contact of relay 1377, the alternate contacts of relays 1378 and 1379, the upper contact of relay 1380, the alternate contacts of relays 1381 and 1382, the upper contact of relay 1383, the alternate contacts of relays 1384 and 1385, the upper contact of relay 1386, the alternate contacts of relays 1387 and 1388, the upper contact of relay 1389, the alternate contacts of relays 1390 and 1391, the upper contact of relay 1392, the alternate contacts of relays 1393 and 1394, the upper contact of relay 1395, the alternate contacts of relays 1396 and 1397, the upper contact of relay 1398, the alternate contacts of relays 1399 and 1400, the upper contact of relay 1401, the alternate contacts of relays 1402 and 1403, the upper contact of relay 1404, the alternate contacts of relays 1405 and 1406, the upper contact of relay 1407, the alternate contacts of relays 1408 and 1409, the upper contact of relay 1410, the alternate contacts of relays 1411 and 1412, the upper contact of relay 1413, the alternate contacts of relays 1414 and 1415, the upper contact of relay 1416, the alternate contacts of relays 1417 and 1418, the upper contact of relay 1419, the alternate contacts of relays 1420 and 1421, the upper contact of relay 1422, the alternate contacts of relays 1423 and 1424, the upper contact of relay 1425, the alternate contacts of relays 1426 and 1427, the upper contact of relay 1428, the alternate contacts of relays 1429 and 1430, the upper contact of relay 1431, the alternate contacts of relays 1432 and 1433, the upper contact of relay 1434, the alternate contacts of relays 1435 and 1436, the upper contact of relay 1437, the alternate contacts of relays 1438 and 1439, the upper contact of relay 1440, the alternate contacts of relays 1441 and 1442, the upper contact of relay 1443, the alternate contacts of relays 1444 and 1445, the upper contact of relay 1446, the alternate contacts of relays 1447 and 1448, the upper contact of relay 1449, the alternate contacts of relays 1450 and 1451, the upper contact of relay 1452, the alternate contacts of relays 1453 and 1454, the upper contact of relay 1455, the alternate contacts of relays 1456 and 1457, the upper contact of relay 1458, the alternate contacts of relays 1459 and 1460, the upper contact of relay 1461, the alternate contacts of relays 1462 and 1463, the upper contact of relay 1464, the alternate contacts of relays 1465 and 1466, the upper contact of relay 1467, the alternate contacts of relays 1468 and 1469, the upper contact of relay 1470, the alternate contacts of relays 1471 and 1472, the upper contact of relay 1473, the alternate contacts of relays 1474 and 1475, the upper contact of relay 1476, the alternate contacts of relays 1477 and 1478, the upper contact of relay 1479, the alternate contacts of relays 1480 and 1481, the upper contact of relay 1482, the alternate contacts of relays 1483 and 1484, the upper contact of relay 1485, the alternate contacts of relays 1486 and 1487, the upper contact of relay 1488, the alternate contacts of relays 1489 and 1490, the upper contact of relay 1491, the alternate contacts of relays 1492 and 1493, the upper contact of relay 1494, the alternate contacts of relays 1495 and 1496, the upper contact of relay 1497, the alternate contacts of relays 1498 and 1499, the upper contact of relay 1500, the alternate contacts of relays 1501 and 1502, the upper contact of relay 1503, the alternate contacts of relays 1504 and 1505, the upper contact of relay 1506, the alternate contacts of relays 1507 and 1508, the upper contact of relay 1509, the alternate contacts of relays 1510 and 1511, the upper contact of relay 1512, the alternate contacts of relays 1513 and 1514, the upper contact of relay 1515, the alternate contacts of relays 1516 and 1517, the upper contact of relay 1518, the alternate contacts of relays 1519 and 1520, the upper contact of relay 1521, the alternate contacts of relays 1522 and 1523, the upper contact of relay 1524, the alternate contacts of relays 1525 and 1526, the upper contact of relay 1527, the alternate contacts of relays 1528 and 1529, the upper contact of relay 1530, the alternate contacts of relays 1531 and 1532, the upper contact of relay 1533, the alternate contacts of relays 1534 and 1535, the upper contact of relay 1536, the alternate contacts of relays 1537 and 1538, the upper contact of relay 1539, the alternate contacts of relays 1540 and 1541, the upper contact of relay 1542, the alternate contacts of relays 1543 and 1544, the upper contact of relay 1545, the alternate contacts of relays 1546 and 1547, the upper contact of relay 1548, the alternate contacts of relays 1549 and 1550, the upper contact of relay 1551, the alternate contacts of relays 1552 and 1553, the upper contact of relay 1554, the alternate contacts of relays 1555 and 1556, the upper contact of relay 1557, the alternate contacts of relays 1558 and 1559, the upper contact of relay 1560, the alternate contacts of relays 1561 and 1562, the upper contact of relay 1563, the alternate contacts of relays 1564 and 1565, the upper contact of relay 1566, the alternate contacts of relays 1567 and 1568, the upper contact of relay 1569, the alternate contacts of relays 1570 and 1571, the upper contact of relay 1572, the alternate contacts of relays 1573 and 1574, the upper contact of relay 1575, the alternate contacts of relays 1576 and 1577, the upper contact of relay 1578, the alternate contacts of relays 1579 and 1580, the upper contact of relay 1581, the alternate contacts of relays 1582 and 1583, the upper contact of relay 1584, the alternate contacts of relays 1585 and 1586, the upper contact of relay 1587, the alternate contacts of relays 1588 and 1589, the upper contact of relay 1590, the alternate contacts of relays 1591 and 1592, the upper contact of relay 1593, the alternate contacts of relays 1594 and 1595, the upper contact of relay 1596, the alternate contacts of relays 1597 and 1598, the upper contact of relay 1599, the alternate contacts of relays 1600 and 1601, the upper contact of relay 1602, the alternate contacts of relays 1603 and 1604, the upper contact of relay 1605, the alternate contacts of relays 1606 and 1607, the upper contact of relay 1608, the alternate contacts of relays 1609 and 1610.

1245, 1240 and 1238 and the upper contact of relay 1236 to ground through the interrupter. Relays 1246 and 1247 lock through their windings and the lower alternate contact of relay 1247, the winding of relay 1248 and the lower contact of relay 1246 to ground. While the grounded segment of the interrupter 1237 is engaged by its brush, relay 1248 is short-circuited and does not operate in series with the locking circuit of relays 1246 and 1247 until the next ungrounded segment of the interrupter 1237 is reached.

When the relays 1241 and 1242 operate, the wipers 1218 1219 and 1220 of switch K¹ are connected through contacts of sail relays, the wipers 1302, 1303 and 1304 of switch G³ and the terminals engaged thereby and from thence to the normal contacts of the relay 1600 of the number indicator. With the wiper 1218 engaging the terminal in its upper group individual to the selected line, no ground is connected to said wiper and therefore no units relay in the number indicator controlled through said wiper will be operated. With the wiper 1219 in engagement with the terminal in its upper group individual to the line selected, a circuit will be closed extending from ground through said terminal and wiper, the upper contact of relay 1242, the upper normal contacts of relays 1243 and 1246, wiper 1303 of switch G³ and the terminal engaged thereby, the next to the uppermost normal contact of relay 1600 and the winding of units relay 1603 to grounded battery. Relay 1603 energizes and locks through its winding and middle contacts, the common locking conductor 1619 and the contact of relay 1502 to ground. Relay 1603 locks before the energizing circuit therefor is opened at the upper normal contact of relay 1243 when said relay energizes as previously described. Simultaneously with the energization of the units relay 1603, a circuit is also established to energize units relay 1604 extending from ground through resistance 1223, the terminal in the upper group engaged by the wiper 1220 and individual to a selected line, the upper contact of relay 1241, the normal contacts of relays 1244 and 1247, wiper 1304 of switch G³ and terminal engaged thereby, the next to the lowermost normal contact of relay 1600, the winding of marginal units relay 1605 and the winding of units relay 1604 to grounded battery. Inasmuch as resistance 1223 is included in this circuit, marginal relay 1605 will not operate but the relay 1604 energizes and locks through its windings and inner upper contacts, the inner upper normal contact of relay 1605 and from thence over the conductor 1619 to ground at the contact of relay 1502. At the time of the energization of relays 1241 and 1242 and before relay

1240 operates, a circuit is also established for relay 1601 extending from grounded battery through the winding of relay 1601, the lowermost normal contact of relay 1600, the wiper 1305 and terminal engaged thereby, the lower normal contact of relay 1240, the alternate contact of relay 1238, and the upper contact of relay 1236 to ground through the interrupter 1237. Relay 1601 energizes and locks through its winding and contact, the winding of relay 1600 and from thence to ground over the common locking conductor 1619. Relay 1600 does not energize in the locking circuit for relay 1601 since it is short-circuited as long as the brush of interrupter 1237 is in engagement with a grounded segment. When an ungrounded segment is reached the short-circuit of relay 1600 is removed and the same operates in series with the locking circuit of relay 1601 to transfer the conductors connected to the armatures of relay 1600 to the normal contacts of relay 1606. At this point in the operation, relays 1243 and 1244 are operated as previously described to associate these relays with the tens relays 1224 to 1227. It will be recalled that of these relays only the relay 1226 is operated when the relay 1234 is energized. Therefore, the operation of relays 1243 and 1244 establishes a circuit extending from ground through the resistance 1249, the normal contact of relay 1227, the contact of relay 1226, the upper alternate contact of relay 1244, the normal contact of relay 1247, the wiper 1304 and contact engaged thereby, the next to the lowermost alternate contact of relay 1600, the next to the lowermost normal contact of relay 1606, winding of marginal tens relay 1611 and the winding of tens relay 1610 to grounded battery. Relay 1610 operates in this circuit but, due to the inclusion of the resistance 1249 therein, marginal relay 1611 does not energize. The energization of relay 1610 prepares a circuit for the tens lamp 3 and closes a locking circuit for itself extending through its winding and inner upper contact, the inner upper normal contact of relay 1611 and thence to ground on the locking conductor 1619. When relay 1600 was energized, a circuit was established for relay 1607 extending from grounded battery through the winding of relay 1607, the lowermost normal contact of relay 1606, the lowermost alternate contact of relay 1600 to wiper 1305 of switch G³ and terminal engaged thereby, the lower normal contact of relay 1245, the alternate contact of relay 1238 and the upper contact of relay 1236 to ground through a conducting segment of the interrupter 1237. The relay 1607 energizes and locks through its contact and winding of relay 1606 to ground on the locking conductor 1619 but relay 1606 does not energize in

this locking circuit inasmuch as the same is short-circuited as long as the brush of interrupter 1237 is in engagement with a grounded segment. When the next ungrounded segment is reached the short-circuit is removed from relay 1245 as previously described and also from the winding of relay 1606 which latter relay thereupon energizes to transfer the conductors connected to the armatures thereof to normal contacts of relay 1612. Following the energization of relay 1245, the relays 1246 and 1247 are operated as previously described to connect their armatures to the conductors extending to the wipers 1203, 1204 and 1205 of the switch M. Since a toll line in the first hundred has been selected, no potential will be connected to any of the wipers of switch M and hence none of the hundreds relays 1614 to 1618 will be energized through contacts of relays 1246 or 1247. When relay 1606 is energized a circuit for operating relay 1613 is established extending from grounded battery through the winding of relay 1613, the lowermost alternate contacts of relays 1606 and 1600, wiper 1305, switch K^1 and terminal engaged thereby, the lower normal contact of relay 1248 and from thence through the interrupter 1237 to ground over the previously described circuits for relays 1601 and 1607. When relay 1613 is energized it locks through its winding and contact and the winding of relay 1612 to ground on the common conductor 1619. Relay 1612 being short-circuited by ground through interrupter 1237, does not energize in series with the locking circuit of relay 1613, until the next ungrounded segment of the interrupter 1237 is reached whereupon said short-circuit is removed and relays 1248 and 1612 are thereupon energized.

The energization of relay 1612 simultaneously closes the prepared circuits for the various lamps to be lighted which indicate the number of the toll line selected by the switch K^1 . None of the hundreds relays 1614 to 1618 being energized a circuit is established for the hundreds lamp 0 extending from grounded battery through said lamp, the upper normal contacts of relay 1617, the lower normal contact of relay 1615, the normal contact of relay 1614 and the lowermost contact of relay 1612 to ground. The lamp 0 is lighted in this circuit. Tens relay 1610 being energized, a circuit is established for lighting tens lamp 3 extending from grounded battery through the inner lower normal contact of relay 1611, through the "tens" lamp 3, the outer upper alternate contact of relay 1610, the lower normal contact of relay 1609, the normal contact of relay 1608 and the lowermost contact of relay 1612 to ground. Units relay 1603 and 1604 being operated, a circuit for lighting the units lamp 6 is established extending

from grounded battery through the outer lower normal contact of relay 1605, the "units" lamp 6, the inner lower alternate contact of relay 1604, the lower alternate contact of relay 1603, the normal contact of relay 1602 and the lowermost contact of relay 1612 to ground.

Operator connects cord circuit A with toll line L.

75

The operator at the third position in the third group observing the number of the line selected, inserts the plug 203 of the cord circuit A into the jack 300 of the selected line L whereupon a circuit is established from grounded battery through the windings of relays 201 and 202 in series, sleeve contacts of plug 203 and jack 300 and the winding of relay 301 to ground. Relay 202, being marginal does not energize in series with relay 301. Relay 301 is energized in the above circuit and its operation closes an obvious energizing circuit for relay 302 which, in operating, connects ground through its contacts to the terminals engaged by the wipers 1215 and 1217 of the switch K^1 . The ground on the terminal engaged by wiper 1217 causes the selected toll line L to test busy to all other switches similar to K^1 associated with other links. The ground on the terminal engaged by the wiper 1215 is extended through the middle contact of relay 1234, the wiper 1206 of switch M and the winding of relay 1309 to grounded battery. Relay 1309 energizes and connects ground at its left-hand contact to the test terminal individual to the second link over which wiper 1525 of the switch E passes thus causing the second link to test busy. The operation of relay 1309 also removes ground from the winding of relay 1306, the holding circuit of which extended through the outer right-hand contact of relay 1308. Relay 1306 thereupon releases to open at its right-hand contact the holding circuit for relay 1308 which latter relay thereupon restores. The release of relay 1306 also disconnects ground from its left-hand alternate contact, which ground had been utilized to short-circuit slow-release relay 1505. This latter relay thereupon energizes in series with the previously described locking circuit for relay 1503. The energization of relay 1505 causes the relay 1502 to operate over a circuit extending from grounded battery through the winding of relay 1502 and the alternate contacts of relays 1506 and 1505 to ground. The removal of ground from the contact of relay 1502 opens the locking circuits for relays 1501, 1503, 1504, 1505 and 1506 which relays thereupon restore. When the alternate contact of relay 1506 is opened the circuit for relay 1502 is broken and this relay, after an interval, releases. The release of relay 1501 opens the holding circuit for re-

130

lay 1507 which thereupon releases to close its normal contact.

- The energization of relay 1502 removes ground from the common locking conductor 1619 and relays 1600, 1601, 1606, 1607, 1612 and 1613 are thereupon restored to normal. Upon the release of relay 1612 and consequent removal of ground from its alternate contact the number indicator relays 10 which have been operated are restored to normal and the lamps which have been lighted are extinguished whereupon the number indicator is again in its normal position.
- 15 The release of relay 1507 and consequent closure of its normal contact establishes a self-interrupting circuit for magnet 1307 which extends from grounded battery, through winding and contact of said magnet, the left-hand normal contact of relay 1306, the wiper 1300 and the normal contact of relay 1507 to ground. The wipers of switch G^3 are thereupon stepped to the next succeeding terminals, which are individual to another operators' position. If the operators of the next and succeeding positions are idle, the apparatus associated with said positions will be in normal conditions and the relays similar to relay 1507 therein will be released. Therefore, ground will be found on each terminal engaged by wiper 1300 of switch G^3 , and said switch will step until the same is restored to normal. If it should happen that the operator at the position individual to the next terminal engaged by wiper 1300, when the same is stepped from the terminal individual to the third operator's position, is making a call, the relay similar to relay 1507, in the calling operator's position apparatus, is energized and another switch similar to G^3 and associated with another link preselected by the allotter E is hunting for said calling operator's position. The energization of said relay similar to relay 1507 removes ground from the terminal engaged by wiper 1300, and the switch G will not instantly step its wipers from the engaged terminals. However, as soon as the other switch similar to switch G^3 , has found the calling operator's position, the relay in said other switch similar to relay 1306 is energized and connects ground through its left-hand alternate contact to the conductor to which are multiplied the wiper 1300, and similar wipers of other position hunting switches individual to the third group of operators. Hence the stepping magnet 1307 of switch G^3 will again be operated to step the wipers of the switch to the next succeeding terminals. It will thus be seen that the switch G^3 will continue to be stepped until the normal terminals thereof are reached.
- 65 When the relay 1308 of switch G^3 releases, as previously described, ground is removed from the left hand contact of said relay and from conductor 1310, thereby causing the release of relays 1200 and 1202. A self-interrupting circuit is thereupon established from magnet 1201, extending from 70 grounded battery, through the contact of said magnet, the outer right-hand normal contact of relay 1202, winding of magnet 1201, the inner right-hand normal contact of relay 1202, and the wiper 1207 of switch 75 M to ground. This self-interrupting circuit is maintained to operate magnet 1201, whereby the wipers of switch M are stepped to their normal positions at which time ground is no longer connected to wiper 1207, 80 and the circuit for magnet 1201 is therefore permanently opened with the result that the wipers of switch M come to rest. When the magnet 1201 starts to return switch M 85 to normal, the energizing circuit for relay 1309 through the wiper 1206 is opened, and said relay thereupon restores to remove the busy condition from the terminal of allotter switch E over which the wiper 1525 passes so that the second link can again be pre- 90 selected.
- At the time that relay 1200 is released by the restoration of relay 1308, ground is disconnected from the contact of relay 1200 or to open the holding circuit for relay 1221 95 of the switch K^1 . This relay thereupon releases and causes the restoration of relay 1234. When the right-hand contact of relay 1234 is opened, relay 1236 of the mechanism N is restored to open the locking circuits for the remaining relays of said mechanism, and these relays are thereupon released to restore the mechanism N to normal. The opening of the inner contact of relay 100 1234 causes the tens relay 1026 to deenergize. 105
- The release of relay 1221 removes the short circuit from the low resistance winding of the differential relay 1232, which short-circuit extended through wiper 1217, but relay 1232 does not release at this time 110 due to current flowing from grounded battery, through the winding and contact of stepping magnet 1222, normal contact of relay 1221, wiper 1217, low resistance winding of relay 1232, and the contact of relay 115 1233 to ground. This circuit overcomes that through the high resistance winding of relay 1232 to prevent said relay from releasing, and said current also operates relay 1222 to step the wipers of switch K^1 120 to the next terminals. If the wiper 1217 encounters ground on the next terminal engaged thereby, indicating a busy line, stepping magnet 1222 will again be operated 125 through said wiper to cause switch K^1 to take another step. It will thus be seen that if the remaining terminals engaged by wiper 1217 are grounded by busy lines, the switch will continue to step until the normal position is reached. When the wiper 1217 steps 130

from the terminal of line L, which has been selected, current no longer flows through the low resistance winding of relay 1232 in series with the magnet 1222, and said low resistance winding is then placed in series only with the high resistance winding of relay 1232. The latter relay being differential, is released, and in so doing causes the release of relay 1233. If the terminal 10 next engaged by wiper 1217, when it is stepped from the terminal of the selected line L, has no ground thereon, thus indicating an idle line, said wiper 1217 comes to rest on said next terminal, and the switch 15 remains in this position until another switch similar to K¹ and associated with another link selects the idle line to which the terminal now engaged by wiper 1217 is individual. Then when the relay of said other 20 switch similar to relay 1221 operates, the conductor to which are multiplied the corresponding terminals engaged by the wipers 1217 of all switches similar to switch K¹ 1222 is grounded, and the stepping magnet 1222 25 will again be operated to move the wipers of switch K¹ to the next succeeding terminals. Upon reaching the next to the last terminal, wiper 1217 finds ground over said multiplied conductor and through the low 30 resistance winding and outer contact, respectively of relays in some other switch similar to the relays 1235 and 1213. From the foregoing description it will be apparent that the switch K¹ will be stepped until 35 the normal positions of the wipers are reached. The apparatus used in selecting an idle toll line and indicating the number of said line to the outgoing operator has now been restored to normal, and is free to 40 be used in establishing another connection.

Selection of a line register and connection thereof to the cord register.

The insertion of the plug 203 of cord circuit A into jack 300, in addition to operating relays 301 and 302, also initiates the selection of a line register such as shown in Fig. 6. When relay 301 operated, as previously described, an obvious energizing 45 circuit for relay 303 was established and by opening its normal contact relay 303 removed ground from the multiple terminals of a plurality of switches similar to switch O, which terminals are individual to the 50 selected line L. As many of the switches O are provided as are necessary to take care of 400 lines extending to a particular distant toll office, but inasmuch as these switches are duplicates of the one shown, it 55 is not deemed necessary to illustrate the same. The switch O, to which a pre-selected link Q is individual, is operated, as 60 will presently appear, to engage wipers 400 to 405 with the terminals individual to the 65 selected toll line L. A plurality of links,

such as Q, serve the group of lines in which line L is located and these links are employed for connecting the line circuit (Fig. 3) to one of a number of line registers through register selecting switches, such as the switch R, which operate to find an idle register while a switch O is seeking the terminals of line L. The switch O and other similar switches are connected in 70 multiple so that the line circuit has access to the terminals of a plurality of switches such as switch R. In this manner the line circuit may be connected to an idle register through any one of a plurality of links such as Q. An idle link Q is preselected by an 75 allotter switch S, which is common to a certain number of the plurality of links, there being other allotter switches similar to S for other groups of links. When a line is taken for use a switch O will immediately 80 be started to hunt for the terminals of said line and a switch R will select an idle line register. When this line is found switch O comes to rest and the allotter switch S, which is also associated with a number of 85 the switches O equal to the number of links Q terminating in the bank of switch S, is then operated to preselect another link similar to the link Q. Then when another line is taken for use, another switch, similar 90 to switch O, will be started through the pre-selected link associated therewith and another register finding switch similar to switch R, will operate. If two or more lines are simultaneously, or practically 95 simultaneously, taken for use, thus removing ground from two or more terminals passed over by wiper 400, the switch O will stop upon the ungrounded terminal first 100 encountered whereupon the switch S will 105 allot another link and thus, through the multiplied connections to the switches O, cause another switch O to start hunting for the next terminal from which ground 110 has been removed.

Returning now to the operation of relay 303, it will be seen that the closure of the left-hand contacts of this relay establishes a circuit extending from ground through 115 said contact, the contact of relay 304, and the winding of relay 309 to grounded battery. Relay 309 energizes to ground the conductor 310 which is common to the group of lines in which line L is located. Ground connected to the contact of relay 309 is extended through the wiper 406 of switch S and the associated terminal of the pre-selected link engaged thereby, the wiper 400 of switch Q, the normal contact of relay 407 120 and the contact and winding of stepping magnet 408 to grounded battery. This circuit also extends through the winding of relay 407 but the normal contact of this relay short-circuits the same and hence it 125 will not operate. The stepping magnet 408 130

is operated in the traced circuit to step the wipers of switch O from their normal positions and on to terminals individual to various toll lines terminating in said switch.

5 When the wiper 400 engages the terminal of the first toll line in its bank, the same will find a ground on this terminal from the normal contact of a relay, similar to relay 303, if this toll line is idle. This ground will 10 again cause stepping magnet 408 to operate to advance the wipers of switch O to the next terminals, and this operation continues until wiper 400 engages the terminal to which the normally grounded contact of relay 303 is connected. This contact now being 15 opened, the short-circuit for relay 407 is removed and this relay energizes in series with stepping magnet 408 over a circuit extending through the windings of magnet 408 and 20 relay 407, wiper 406, and from thence over conductor 310 to ground through the contact of relay 309. The stepping magnet 408, now being in series with the relay 407, will no longer operate and the wipers of switch O 25 will come to rest upon the terminals individual to the selected line L. The energization of relay 407 establishes an operating circuit for relays 409 and 304 extending from grounded battery through the winding 30 of relay 304, the right-hand alternate contact of relay 303, wiper 400 and terminal engaged thereby, the alternate contact of relay 407 and the winding of relay 409 to ground. Relays 304 and 409 operate and the 35 former thereby opens the energizing circuit for relay 309 which thereupon releases to disconnect ground from the common conductor 310. At the time relay 303 operated to establish an energizing circuit for the 40 stepping magnet 408 to step the wipers of switch O from their normal positions, a parallel circuit was also established for relay 410 and this relay thereupon operated to initiate the operation of the line register selecting switch R. The closure of the contact of relay 410 establishes a circuit extending from ground through said contact, the wiper 411 of switch R, the normal contact of relay 417 and the contact and winding of the 45 stepping magnet 418 to grounded battery. The normal contact of relay 417 short-circuits this relay but the stepping magnet 418 operates to step the wipers 411 to 416 of switch R from their normal positions. The 50 busy condition of the line register is denoted by ground upon the multiple terminals engaged by wiper 411, said ground being connected to the terminals by the energization of relays similar to relay 417 of other 55 switches which are connected to the busy line registers. Thus, as long as wiper 411 encounters ground upon the terminals engaged thereby, the stepping magnet 418 will 60 continue to operate. When a terminal of an 65 idle register is encountered wipers of switch R will be brought to rest upon the terminals individual to the idle line register due to the failure of the stepping magnet 418 to operate in series with the relay 417 over a circuit extending through the windings of 70 magnet 418 and relay 417, and the contact of relay 410 to ground. Relay 417, however, energizes in this circuit to connect ground to the multiple terminal engaged by wiper 411 to cause the line register to test busy to 75 other switches similar to R.

At the time relay 409 energized the closure of the right-hand contact thereof established an obvious self-interrupting circuit for stepping magnet 419 of the allotter 80 switch S, and this stepping magnet thereupon operates to step its wipers 406 and 420 to preselect an idle link Q. The wipers of the switch S are brought to rest upon the terminals of an idle link by the absence of 85 ground upon the terminal individual to said link engaged wiper 420. When wiper 406 is stepped from the terminal engaged thereby and individual to link Q, ground is removed from the winding of relay 410, but previous to this time relay 409 is operated to close, at its left-hand contact, an obvious holding circuit for relay 410 and hence this relay will 90 remain energized.

The operation of relay 417 of switch R 95 and the subsequent connection of ground to the wiper 411 establishes an obvious operating circuit for the differential relay 500, which extends through the high resistance right-hand winding of said relay to ground- 100 ed battery. The energization of relay 500 in this circuit establishes an obvious operating circuit for the slow-to-release relay 501 which, at its right-hand contact, connects ground to the common conductor 502 to 105 which relays of the line register are connected. The closure of the left-hand contact of relay 501 establishes an energizing circuit for relay 305, which circuit extends from grounded battery through the winding of relay 305, the left-hand normal contact of relay 306, wipers 405 and 416 and terminals engaged thereby, the normal contact of relay 503 and the left-hand contact of relay 501 to ground. Relay 305 operates in this circuit and locks in a circuit extending through its winding and right-hand alternate contact, and from thence in parallel through the windings of relays 306 and 307 to ground at the left-hand alternate 110 contact of relay 303. Relays 306 and 307 do not energize in this locking circuit since the same are short-circuited by the ground connected to the left-hand contact of relay 501 and extending through the wipers 416 and 115 405 and terminals engaged thereby, the left-hand normal contact of relay 306 and the right-hand alternate contact of relay 305.

The line circuit and register are now in 120 condition to receive impulses from the cord 130

circuit register (Fig. 1) to operate the storing and transmitting relays of said line register. The operation of relay 305 establishes a circuit extending from ground through the 5 normal contact of relay 307, the outer left-hand contact of relay 305, resistance 308 in shunt of the winding of relay 301, the sleeve contacts of jack 300 and plug 203, and the windings of relays 202 and 201 in series to 10 grounded battery. The marginal relay 202 operates in this circuit and the closure of the contact of this relay establishes an obvious energizing circuit for relay 205. The latter relay thereupon locks through its inner 15 right-hand contact of ground at the contact of relay 201. The operation of relay 205 closes a circuit extending from ground through the outer left-hand contact of relay 205, the outer left-hand normal contact of 20 relay 206 and the winding of relay 207 to grounded battery. Relay 207 operates to connect the tip and ring conductors of the cord circuit to the conductors 208 and 209, which lead to contacts of relay 210. These 25 conductors are common to the various cord circuits similar to cord circuit A at the outward operator's position. The energization of relay 205 connects ground at the contact of relay 201 through the outer right-hand contact of relay 205, the inner right-hand normal contact of relay 206 to the winding of relay 200. Battery having previously been connected to relay 200 through the alternate contact of the transfer relay 111, the relay 30 200 now energizes. The lamp 211 is also lighted at this time to indicate to the outward operator that the call which was registered on the various cord register relays is now being transmitted to the line register. 35 After the operation of relay 200 a circuit is closed for relay 212, following the engagement of the contact of an interrupter 213 to the grounded segment thereof, which circuit extends from grounded battery 40 through the winding of relay 212, the normal contacts of relay 214 and the contact of relay 200 to ground through the interrupter 213. Relay 212 energizes and the operation thereof establishes a circuit for 45 relay 214 extending from grounded battery through the winding and contact of relay 212, winding of relay 214, the inner right-hand normal contact of relay 206, the outer right-hand contact of relay 205 and 50 the contact of relay 201 to ground. Relay 212 is locked in this circuit but relay 214 is short-circuited through its normal contact and the contact of relay 212 as long as the brush of interrupter 213 engages a grounded segment. When an ungrounded segment 55 is reached relay 214 energizes. When the brush of interrupter 213 next reaches a grounded segment, this ground is extended through the alternate contact of relay 214, 60 the right-hand normal contact of relay 215

and the winding of relay 210 to grounded battery. Relay 210 energizes to connect the conductors 208 and 209 to the wipers 216 and 217 of switch T. At the same time that relay 210 is energized a circuit is established 70 for stepping magnet 218 of switch T extending from grounded battery through the winding of this magnet, the left-hand normal contact of relay 215, and from thence to ground over the circuit described for relay 210. The stepping magnet 218 energizes but the stepping pawl thereof is so arranged that the wipers of switch T will not be moved until the circuit for the stepping magnet is opened and said magnet released. 75 80

Transfer of record from cord register to the selected line register.

In the description of the operation of the 85 cord circuit register it will be recalled that register relays 116 and 117 of the first group were energized and relays 114 and 115 of said group remained inert. Under this condition and with wipers 216 and 217 of switch 90 T in their first positions, a circuit is established from ground through the resistance 131 at relay 115, the normal contact of this relay, the wiper 216 and terminal engaged thereby, the left-hand contact of relay 210, conductor 208, the left-hand alternate contact of relay 207, the alternate contact of relay 204, the tip contacts of plug 203 and jack 300, the outer left-hand normal contact of relay 307, the inner right-hand normal contact of relay 306, the wipers 403 and 414 and terminals engaged thereby, winding of relay 504, middle normal contact of transfer relay 600, and right-hand winding of 95 register relay 602 to grounded battery. Relay 504 operates in this circuit but due to the inclusion of the resistance 131 therein, relay 602 will not operate. Inasmuch as relay 114 is not operated, the ground at its lower contact will not be extended through wiper 217 and conductor 209 to the ring contacts of plug 203 and jack 300, and from thence to the winding of register relay 603, and this latter relay will therefore remain 100 inert. The energization of relay 504 establishes a circuit for relay 601 extending from grounded battery through the winding of relay 601, the upper normal contact of relay 600 and the contact of relay 504 to ground. Relay 601 operates and through 105 its contact closes a circuit through the winding of relay 600 and the right-hand contact of relay 501 to ground, but relay 600 is not energized since it is short-circuited by the ground at the contact of relay 504 through the upper normal contact of relay 600 and the contact of relay 601. When the brush of interrupter 213 next engages an ungrounded segment, relays 210 and 504 and 110 magnet 218 release. The release of relay 115 120

125

130

504 removes the short-circuit for relay 600 which thereupon energizes and locks in series with relay 601. The restoration of the magnet 218 steps the wipers of switch T 5 to position 2.

When the brush interrupter 213 again connects ground to the contact of relay 200, relay 210 and magnet 218 again operate. Register relays 116 and 117 are now associated, respectively, with the tip and ring contacts of plug 203 through wipers 216 and 217 in position 2. The operation of relay 116 establishes a circuit from ground through the lower alternate contact of relay 116, the wiper 216 and from thence over the previously described circuit through the tip contacts of plug 203 and jack 300 as far as the middle normal contact of transfer relay 600. This relay being now energized, 10 the circuit is extended through the middle alternate contact of said relay, the middle normal contact of transfer relay 604 and the righthand winding of register relay 606 to grounded battery. Since the resistance 132 15 at relay 116 is not included in this circuit, both relays 504 and 606 will operate. Relay 606 locks through its left-hand winding and contact to ground at the right-hand contact of relay 501. It will be recalled that relay 20 117 is also operated and a circuit will therefore be established extending from ground through the lower contact of relay 117, wiper 217 in position 2, the right-hand contact of relay 210, conductor 209, the right-hand 25 alternate contact of relay 207, the ring contacts of plug 203 and jack 300, the inner left-hand normal contact of relay 307, the outer right-hand normal contact of relay 306, the wipers 402 and 413 and terminals 30 engaged thereby, the lower alternate contact of transfer relay 600, the lower normal contact of relay 604 and the winding of relay 607 to grounded battery. Relay 607 energizes and locks through its left-hand contact to ground at the right-hand contact of relay 501. The operation of relay 504 and the circuit for relay 606 closes a circuit for relay 605 extending from grounded battery 35 through the winding of relay 605, the upper normal contact of relay 604, the upper alternate contact of relay 600 and the contact of relay 504 to ground. Relay 605 energizes and locks in a circuit through its winding and contact, the winding of relay 604 and from thence to ground at the right-hand contact of relay 501. Relay 604 does not 40 operate in this circuit due to its being shunted by the ground at relay 504 while this relay remains operated. When the next release of relay 504 at the time the brush of interrupter 213 next engages an ungrounded segment, the short-circuit for relay 604 is removed and this relay operates in series 45 with relay 605. It will thus be seen that the engagement of wipers 216 and 217 with two

associated contacts is necessary to convey the conditions existing at the lower contacts of the cord register relays in the first group. Upon the engagement of the brush of interrupter 213 with the next ungrounded segment, which results in the second release of relay 504 to remove the short-circuit from relay 604, relay 210 and magnet 218 also release whereupon switch T is stepped to engage its wipers with the third contacts. 50 The second group of cord register relays, of which relay 119 is energized, are now associated with the conductors 208 and 209. The operation of relay 119 disconnects the resistance 133 from the third terminal upon which wiper 216 is now resting. Ground is connected directly to the alternate contact of relay 119 through wiper 216 and from thence, after relay 210 is again energized in response to the engagement of the 55 brush of interrupter 213 with a grounded segment, over the previously described circuit through the tip contacts of the plug and jack as far as the middle normal contact of relay 604. This relay now being energized 60 a circuit is extended through the middle alternate contact of relay 604, the middle normal contact of relay 608 and the right-hand winding of relay 610 to grounded battery. Relays 610 and 504 operate in this circuit and the former locks through its left-hand contact to ground at the right-hand contact of relay 501. The operation of relay 504 establishes a circuit for relay 609 65 through the upper alternate contacts of relays 600 and 604 and the normal contact of relay 608. Relay 609 energizes and locks through its contact and the winding of relay 608 to ground at the right-hand contact of relay 501. Relay 608 is not energized 70 in this circuit for the same reason referred to with respect to relays 600 and 604. Inasmuch as relay 118 of the second group of cord register relays is not operated, the ground at the lower contact of said relay will not be extended through the wiper 217 over the ring contacts of the plug and jack to relay 611, and this latter relay will therefore remain inert. At the next interruption 75 of the ground connection at interrupter 213, relay 210 and magnet 218 again release and the wipers of switch T are stepped to position 4. The relays 120 and 121 are now associated with the wipers 216 and 217. Relay 504 again releases to remove the short-circuit for relay 608 which energizes in series with relay 609. 80

Upon the next operation of relay 210 and magnet 218, in response to the continued rotation of interrupter 213, a circuit is established from ground through the resistance 134, the normal contact of relay 120, the wiper 216 in position 4, and from thence over the previously described circuit through the tip contacts of plug and jack, 85

the winding of relay 504, the middle alternate contacts of relays 600, 604 and 608, the middle normal contact of relay 612 and the right-hand winding of relay 614 to ground. Relay 614 is not energized in this circuit due to the inclusion of the resistance 134, but relay 504 energizes to establish an energizing circuit for relay 613 through the upper alternate contacts of relays 600, 604 and 608 and the upper normal contact of relay 612. Relay 613 locks in series with the winding of relay 612 but the latter relay does not energize due to the short-circuit established by relay 504. Relay 121 is not energized and therefore ground will not be connected to the ring contacts of the plug and jack so that relay 615 will fail to operate. The interrupter 213 next causes the release of relays 210 and 504 and the magnet 218 with the result that the wipers of the switch T are stepped to position 5 to associate the third group of cord register relays with the wipers 216 and 217. The operation of successively associating the various groups of cord register relays with the mechanism of the line register causes the operation of the remaining transfer relays 616, 620, 624 and 628 and the associated relays 617, 621, 625 and 629 in the same manner as described in connection with other similar relays. Certain combinations of register relays 618, 619, 622, 623, etc., and register relays individual to the number digits, which have been omitted from the showing, are also operated or remain inert in accordance with the condition of relays in the corresponding groups in the cord register circuit. Bearing in mind that relay 124 of the third group and relays 126 and 128 of the last group are energized, it will be apparent that relays 622, 627 and 630 will energize and lock and relays 618, 619, 623, 626 and 631 will remain inert.

After the potentials at the last group of cord register relays have been transmitted to the line register and relays 629 and 630 have operated, relays 210 and 504 and magnet 218 release due to the engagement of the brush of interrupter 213 with an ungrounded segment and relay 628 energizes in response to the release of relay 504. The release of magnet 218 now steps the wipers of switch T to position 17, and inasmuch as the seventeenth and succeeding positions of wipers 216 and 217 are not connected to any of the cord register relays, it will be obvious that the operation of line register relays will cease. Upon the operation of relay 629 a circuit is established extending from grounded battery through the winding and contact of relay 629, the winding of relay 503 and the right-hand contact of relay 501 to ground. Relay 503 is operated in this circuit and in opening its normal contact removes ground from the winding of relay

305. It will be recalled that this ground short-circuited the relays 306 and 307 when relay 305 is operated. Upon the removal of this ground relays 306 and 307 operate in parallel through the locking circuit described for relay 305 and the latter relay therefore remains energized. The operation of relay 307 connects the tip and ring conductors of the cord circuit A to toll line L. The operation of relay 307 also removes the ground connection from its normal contacts through resistance 308 whereupon relay 202, which was energized through this resistance, is released. The release of relay 202 opens the original energizing circuit for relay 205 but this relay is now locked through its inner right-hand contact to ground at the contact of relay 201.

At the time the wipers of switch T were stepped to position 17 a circuit was established for relay 215 extending from grounded battery through the winding of relay 215 and the wiper 219 in position 17 to ground. Relay 215 energizes in this circuit and in so doing establishes a self-interrupting circuit for the stepping magnet 218 extending from grounded battery through the winding and contact of said magnet, the left-hand alternate contact of relay 215 and the wiper 219 to ground. Magnet 218 operates and releases to step the wipers of switch T over the succeeding terminals thereof until said wipers have reached their normal positions where ground is no longer found upon the terminal engaged by wiper 219. Magnet 218 will then cease to operate and the wipers of the switch will be brought to rest. The movement of wiper 220 to position 17 closes an obvious energizing circuit for relay 113 of the cord register and this relay, in operating, disconnects ground from its normal contact to open the locking and holding circuits of the transfer and register relays of the cord circuit, whereupon all of these relays are restored to normal and the register is then in condition for another operation.

The energization of relay 215 also establishes a circuit for relay 206 extending from grounded battery through the winding and continuity contacts of relay 206, the inner left-hand contact of relay 205 and the inner right-hand contact of relay 215 to ground. Relay 206 energizes in this circuit and locks through its left-hand alternate contact, the outer contact of relay 205 and the contact of relay 201 to ground. In opening its left-hand normal contact relay 206 causes the release of relay 207 to connect the cord circuit A through normal contact of relay 207 and the alternate contact of relay 204 to the toll line L. The opening of the inner right-hand contact of relay 206 breaks the holding circuit through the windings of relays 212 and 214 and these relays thereupon restore to normal. Relay 200 also releases

and lamp 211 is extinguished due to the release of the transfer relay 111 and energization of relay 206. Relays 201, 204, 205 and 206 of the apparatus individual to the 5 cord circuit A are now operated and remain in this condition throughout the duration of the call.

10 *Association of signaling apparatus for transmitting supervisory signals with the selected toll line.*

Referring again to the operation of relay 307, it will be seen that when the outer 15 right-hand contact of this relay is closed a circuit will be established from ground through this contact and the winding of relay 311 to grounded battery. The operation of relay 311 establishes an energizing 20 circuit for the slow-to-release relay 319 extending from grounded battery through the normal contact of differential signal receiving relay 320, the winding of relay 319 and the alternate contact of relay 311 to ground. 25 The energization of relay 319 disconnects the right-hand winding of the signal receiving relay 321 from the signal receiving conductor 448 to prevent the operation of relay 321 while relay 319 is operated. The 30 operation of relay 311 also closes an operating circuit for relay 312 extending from grounded battery through the right-hand contact of relay 313, winding of relay 312, inner right-hand normal contact of relay 314, normal contact of relay 315, and the alternate contact of relay 311 to ground. Relay 312 energizes and locks through its winding and inner left-hand contact to ground. The operation of relay 312 establishes an obvious energizing circuit for relay 316 which then locks through its winding and inner contact to ground at the left-hand normal contact of relay 314. The 40 operation of relay 316 prepares an energizing circuit for relay 315, which is not closed until relay 313 is energized. When relay 312 operates the closure of the inner right-hand contact thereof connects ground through the outer right-hand normal contact of relay 314 and the outer normal contact of slow-to-release relay 317 to a terminal individual to line L in the bank of the switch U over which wiper 421 passes. The 45 switch U is common to all of the toll lines in the group in which line L is located and is designed to connect the apparatus of Fig. 3 with that associated with the sending distributor SD, which is employed for transmitting the codes of impulses to the distant toll office to control the supervisory signals 50 thereto. This sending distributor SD is preferably of a type similar to distributors employed in printing telegraphy and is operated in synchronism with the receiving distributor RD (Fig. 11), located at the

distant office whereby the codes of impulses from the outward office may be transmitted to said distant office to indicate at the latter office the particular toll line which has been taken for use. In accordance with the 70 present invention the sending and receiving distributors SD and RD are employed only for the purpose of transmitting the supervisory codes of signals, and in order that the impulses from the line register (Fig. 6) 75 may be transmitted to the distant office to operate the call indicator (Fig. 10) thereat, additional sending and receiving distributors SD¹ and RD¹ are provided, these distributors being common to all of the line registers. Sending and receiving equipment represented by the rectangles SD² and RD² and similar to that shown associated with the distributors SD¹ and RD¹, may be employed for transmitting call indicator signals from the distant office to the outward office when a call is initiated at the former. 80

Returning to the operation of relay 312, it will be recalled that the closure of the inner right-hand contacts of this relay connected ground to a terminal of the row over which wiper 421 passes. The closure of the outer right-hand contact of relay 312 establishes a circuit for relay 318 extending from grounded battery through the winding of said relay 318, the inner normal contact of relay 317 and the outer right-hand contact of relay 312 to ground. Relay 318 then operates and establishes a self-interrupting circuit for the stepping magnet 428 of switch U, said circuit being traceable from grounded battery through the winding and contact of magnet 428, the left-hand contact of relay 429 and the contact of relay 318 to ground. Stepping magnet 428 operates the wipers 421 to 427 of switch U causing them to seek the terminals individual to the toll line L. This operation of the switch continues as long as the wiper 421 does not encounter ground upon the associated terminals, but as soon as said wiper engages the terminal to which ground has been connected by the operation of relay 312 this ground is extended through said wiper and the left-hand winding of relay 429 to grounded battery. Relay 429 operates in this circuit to open, at its left-hand contact, the operating circuit for magnet 428 whereupon the switch U comes to rest upon the terminals individual to the toll line L. With the wipers of switch U engaging these terminals the apparatus is in condition to transmit a code of impulses through the distributor SD to the receiving distributor RD over a common signaling path P terminating in windings of polar relays 430 and 1130. Each of the toll lines in the group including line L has assigned thereto a definite code of impulses which is determined by the position of wipers 421 to 427 of switch U. In the present arrangement the code for line L 130

consists of five impulses which are successively transmitted and which comprise two positive impulses, a negative impulse a positive impulse and then a negative impulse in 5 the order named.

When relay 429 operates, as previously described, a circuit is established for the start magnet 431 of the sending distributor, said circuit extending from grounded battery 10 through the ring 432 of the distributor, brush arm 433, start segment 434, the outer right-hand contact of relay 429 and the winding of magnet 431 to ground. The magnet 431 is energized and thereby releases brush 15 arm 433 of the sending distributor which thereupon makes a complete revolution. As soon as the brush arm 433 passes beyond start segment 434, the energizing circuit for the start magnet is opened and the armature of 20 said magnet is thereby restored to normal in the path of rotation of the brush arm 433 so that this arm is stopped by the armature upon completing its revolution. Upon engagement of the brush arm 433 with segment 25 435 at the beginning of revolution of said arm a circuit is established from the positive pole of battery through the segment 435, brush arm 433, ring 436, and from thence over one path through the lower winding of 30 polar relay 430 and the artificial line to ground, and over another path through the upper winding of relay 430, the conductor P, both windings of polar relay 1130 and the artificial line to ground. The closure of this 35 circuit has no effect upon the polar relay 430 but causes relay 1130 to close its upper contact. A circuit is thereby established extending from grounded battery through the upper contact of relay 1130, segment 1100 of 40 distributor RD, brush arm 1101, segment 1102 and the winding of start magnet 1103 to ground. Magnet 1103 operates to release the brush arm 1101 so that the same will 45 make a complete revolution in synchronism with the brush arm 433 of the distributor SD. During the rotation of brush arms 433 and 1101, the impulses are transmitted over the common conductor P in accordance with the code designation of the toll line L. In order 50 that the transmitted code combination may be translated into suitable signals for appropriate toll lines, the invention preferably includes the provision of receiving apparatus associated with the receiving distributor RD, 55 which is selectively responsive to the code combination to cause the operation of signals individual to the various toll lines. The selective receiving apparatus, as herein shown, includes a plurality of locking relays 1104 to 1109, the locking circuits of which are controlled by common relay 1110. The apparatus further includes a pyramid relay combination of a type well-known in the signaling art, the relays of this combination being 60 indicated by the numerals 1111 to 1125. In

accordance with the code signaling impulses transmitted, the apparatus including the locking and pyramid relays responds to provide a path through the contacts of said relays over which the signal individual to the toll line selected is operated. 70

Returning now to the operation of the sending distributor SD, when the brush arm 433 passes from the start segment 434 to release the start magnet 431 and then 75 engages segment 437, a circuit is established from grounded battery through the ring 432, brush arm 433, segment 437 and the winding of relay 438 to ground. Relay 438 operates and establishes a circuit 80 extending from grounded battery through the contacts of relay 438, the wiper 422 and terminal engaged thereby, and the winding of relay 313 to ground. Relay 313 energizes to disconnect battery from the locking circuit of relay 312 and this relay thereupon releases. The operation of relay 313 closes the previously described circuit which was prepared for relay 315 by the energization of relay 316 and relay 315 thereupon 90 energizes. When relay 315 operates the same locks in a circuit extending from grounded battery through the inner alternate contact and winding of relay 315 and the left-hand normal contact of relay 314 95 to ground. The release of relay 312 removes ground from the winding of relay 318, which relay thereupon deenergizes to disconnect ground from the stepping magnet 428 of switch U so that upon the release of the relay 428, at the termination 100 of the rotation of the distributor SD, the circuit for said stepping magnet will not be closed and the wipers of switch U will 105 therefore be maintained in their positions in contact with the terminals individual to the toll line L. The opening of the inner right-hand contact of relay 312 also removes ground from the terminal engaged by wiper 421 to open the original energizing 110 circuit for relay 429 but this relay is maintained energized as long as relay 438 is operated; the holding circuit for relay 429 being traceable from grounded battery 115 through the right-hand contact of relay 438 and the right-hand winding of relay 429 to ground. Relay 438 is maintained in its operated condition as long as the brush arm 433 engages the segment 437.

As soon as the brush arm 1101 of distributor RD engages segment 1126 at the beginning of rotation of said arm, a circuit is established from grounded battery through ring 1127, brush arm 1101, segment 1126 and the winding of relay 1110 120 to ground. This relay energizes and remains in this condition as long as brush arm 1101 is in engagement with segment 1126. In energizing, relay 1110 connects 125 ground to its contact to prepare a locking 130

circuit for such relays 1104 to 1109 as are energized by the transmission of the code signals over the common signaling path.

- Directly following the energization of relay 438 when the brush arm engages segment 437, said brush arm engages the first sending segment 439 and thereby establishes a circuit extending from the positive pole of battery through the wiper 427 and terminal engaged thereby, segment 439, brush arm 433, ring 436, and from thence over the previously described path through the windings of polar relays 430 and 1130 to ground. The roller relay 1130 then closes its upper contact. When this impulse is transmitted to brush arm 1101 is in engagement with segments 1128 and 1129. Inasmuch as the lower contact of polar relay 1130 is opened at this time, the battery at the polar relay will not be connected to segment 1129 and therefore a circuit will not be established for the first locking relay 1104. The second impulse of the code combination is transmitted when brush arm 433 engages segment 440 and brush 1101 engages segment 1131. The circuit for this impulse extends from the positive pole of battery through the wiper 426 and terminal engaged thereby, segment 440, brush arm 433, ring 436, and then over the conductor P through the windings of the polar relays 430 and 1130. This positive impulse again causes polar relay 1130 to close its upper contact. This disconnects battery from the lower contact of the polar relay and hence locking relay 1105 will not be operated through segments 1129 and 1131. The third impulse to be transmitted is of negative polarity which is connected to the wiper 425 and terminal engaged thereby, and upon engagement of brush arm 433 with segment 441, and the brush arm 1101 with the segment 1132, this impulse will be transmitted over an obvious path to cause relay 1130 to close its lower contact. A circuit is thereupon established extending from grounded battery through the lower contact of relay 1130, segment 1129, brush arm 1101, segment 1132 and the right-hand winding of relay 1106 to ground. Relay 1106 energizes and locks through its left-hand winding and contact to ground at the contact of relay 1110. Brush arm 433 then successively engages segments 442 and 443 to transmit the remaining two impulses of code combination. These impulses are received at the time the receiving distributor brush arm is in engagement with segments 1133 and 1134, respectively. The fourth impulse transmitted being of positive polarity, it will be obvious from an understanding of the previous description that relay 1107 will not be energized. The fifth impulse of negative polarity causes the operation of relay 1108 which then locks through its left-hand winding and contact to ground at the contact of relay 1110. Thus, in the transmission of the code impulses for toll line L, relays 1106 and 1108 have been caused to operate and lock. When brush arm 433 engages segment 444 an impulse of positive polarity is transmitted over the path P from the normal contact of relay 447. This positive impulse is transmitted at the time brush arm 1101 is in engagement with segment 1135, and in closing the upper contact of relay 1130 prevents a circuit from being established for relay 1109. Before the brush arm 433 has passed from engagement with segment 444 the circuit for relay 438, through the segment 437, is opened and relay 438 releases to cause the deenergization of relay 429. The removal of battery from contacts of relay 438 when the same releases opens the energizing circuit for relay 313, which thereupon restores to break the original energizing circuit for relay 315 but the latter relay remains energized in the locking circuit described therefor. The release of relay 313 again connects battery to its normal contacts but relay 312 will not energize due to the operation of relay 315, and relay 314 will not energize due to the operation of relay 311. The battery of negative polarity connected to the segment 445, which is next engaged by brush arm 433, sends an impulse over the path P to cause relay 1130 to close its lower contact. At this time brush arm 1101 has passed from segments 1129 and 1135, and hence the closure of the lower contact of relay 1130 has no effect upon the receiving apparatus.
- The effect of the operation of relays 1106 and 1108 will now be described. By the energization of relay 1106, a circuit is established for pyramid relays 1112 and 1113 extending from grounded battery through the windings of said relays in series and the contact of relay 1106 to ground. When brush arm 1101 engages segments 1137 and 1138, relay 1108 has already been energized and a circuit will therefore be established extending from the negative pole of 120 volt battery through the normal contact of relay 1109, segment 1137, brush arm 1101 and segment 1138, the right-hand alternate contact of relay 1108, the left-hand normal contact of relay 1111, the left-hand alternate contact of relay 1112, the right-hand normal contacts of relays 1114 and 1119, the start conductor 700 and the left-hand winding of the differential relay 702 to ground. The effect of the closure of this circuit will presently be described. When the brush arm 1101 moved from its normal position the circuit of start magnet 1103 was opened and this magnet released to return its armature into the path of brush

arm 1101 so that the rotation thereof will be stopped after the same has passed beyond segments 1137 and 1138 and engaged segments 1100 and 1102. The disengagement of the brush arm 1101 from the segment 1126 opens the holding circuit for relay 1110 which thereupon restores to open the locking circuits of relays 1106 and 1108, which thereupon release. The release of relay 1106 opens the energizing circuit for relays 1112 and 1113, which thereupon restore. However, before relays 1106 and 1108 release, the impulse of negative polarity transmitted from 120 volt battery, as previously described, has become effective to energize the differential relay 702, which thereupon locks through its right-hand alternate contact. This impulse is also transmitted through the right-hand winding of the differential relay 703, which relay responds to this impulse but does not lock inasmuch as the slow-release relay 704 is, at this time, in its normal condition. At the termination of the momentary impulse over conductor 700, relay 703 will therefore release and a circuit is established for relay 704 extending from ground through the winding of said relay, the normal contact of relay 703 and the right-hand alternate contact of relay 702 to grounded battery. The operation of relay 704 has no effect at this time. When relay 703 energized a circuit was established for the slow-to-operate and release relay 705 extending from grounded battery through the right-hand alternate contact of relay 702, the right-hand alternate contact of relay 703 and the winding of relay 705 to ground. However, due to its slow-operating nature relay 705 will not close its contacts during the energization of relay 703. The closure of the right-hand alternate contact of relay 702 establishes a circuit for the guard lamp 706, individual to the toll line L at the incoming office, to light this lamp whereby the incoming operator is informed that a call is being extended over said line. The circuit for lamp 706 extends from grounded battery through the right-hand alternate contact of relay 702, the lower normal contact of relay 707 and the lamp 706 to ground. The distributors SD and RD and apparatus associated therewith having now been restored to normal, with the exception of the switch U, the wipers of which are still in engagement with the terminals individual to toll line L, said apparatus is again in condition to transmit another code of impulses either for line L or for another line in the same group.

Incoming operator responds to the call on toll line L.

65 The incoming operator, upon observing the lighted condition of guard lamp 706, re-

sponds to the call by first operating the assignment key 708, which establishes a circuit extending from grounded battery through the right-hand alternate contact of relay 702, contacts of assignment key 708 and the assignment lamp 711 to ground. The lamp 711 lights in this circuit and said lamp, which is individual to the toll line L, provides an indication to the incoming operator as to which toll line has been taken so that while she is awaiting the operation of the call indicator (Fig. 10) to indicate the number of the wanted line, she may attend to the supervision of other lines under her control. The operation of the assignment key 708 also causes the energization of relays 701 and 709. The circuit for relay 701 extends from ground at the upper normal contact of relay 916 through the winding of relay 701, contacts of assignment key 708 and the right-hand alternate contact of relay 702 to grounded battery. The circuit for relay 709 extends from ground through the winding of relay 709, and from thence in parallel over the energizing circuit of relay 701. Relay 709 locks in a circuit extending from ground through its winding and right-hand contact and the left-hand contact of slow-to-release relay 901 to grounded battery. The operation of relay 709 has no effect at this time. The energization of relay 701 establishes an operating circuit for slow-to-operate and release relay 714 through the winding and right-hand continuity contacts of relay 714, the left-hand contact of relay 713, the outer right-hand normal contact of relay 712 and the alternate contact of relay 701 to ground. This relay energizes and locks through its right-hand alternate contact, the normal contact of the slow-to-release relay 715, the outer right-hand normal contact of relay 712 and the alternate contact of relay 701 to ground. Inasmuch as relay 714 is slow-to-operate a circuit will be established, before relay 714 has opened its continuity contacts, extending from grounded battery through the winding of relay 1139, associated with the sending distributor mechanism SD², similar in all respects to distributor SD, the inner right-hand contact of relay 713, the winding and continuity contacts of relay 716, the left-hand continuity contacts of relay 714, and from thence over the energizing circuit for the latter relay. In this circuit described for relays 716 and 1139, these relays energize and relay 716 locks through its winding and right-hand alternate contact to ground. The operation of relay 716 establishes a circuit extending from ground through the inner left-hand contacts of relay 716, normal contact of the slow-to-release relay 717, the winding of relay 718 and the right-hand alternate contact of relay 702 to grounded battery. The

closure of the contact of relay 718 connects battery through the winding of relay 717 to ground at the left-hand normal contact of relay 712, but relay 717 does not energize in this circuit due to its being short-circuited by the ground connected to the inner left-hand contact of relay 716 and extended through the normal contact of relay 717. The energization of relay 716 also connects ground to the individual signal conductor 719 through the outer left-hand contact of said relay, and this ground is extended to a terminal individual to the toll line L and included in a switch similar to switch U in the mechanism SD². The operation of relay 1139 connects ground through its contact to cause the energization of a relay in the mechanism SD² similar to relay 318, and the energization of this latter relay causes the rotary switch to step in the same manner as previously described for switch U until the ground from the outer left-hand contact of relay 716 is encountered whereupon the rotary switch stops upon the terminals individual to the toll line. The sending distributor of the mechanism SD² is now operated in the same manner as described in connection with the distributor SD to send a code of impulses, individual to toll line L, to the outward office where it is received at the mechanism RD² which includes apparatus similar to that associated with the receiving distributor RD. Transmission of this code of impulses to the outward office results in the release of the line register of Fig. 6, in a manner presently to appear, whereby the codes established by the relays in said register are transmitted to the call indicator before the incoming operator to light the proper lamps at said indicator.

After the rotation of sending distributor SD² the relay in said mechanism similar to relay 438 is operated to connect battery to conductor 1140 to effect the energization of relay 713. When this relay operates, the locking circuit of relay 716 is opened and the latter relay deenergizes. The restoration of relay 716 removes the short-circuit for relay 717 which thereupon operates over the circuit previously described therefor through the winding and contact of relay 718. The operation of relay 717 has no effect at this time.

The code of impulses above referred to is transmitted over the common signaling path P from the sending mechanism SD² to the receiving distributor mechanism RD², which is similar in all respects to the mechanism RD. This receiving mechanism operates to select the signaling conductor 448 individual to toll line L and similar to conductor 700. In accordance with the code of impulses transmitted locking relays in the mechanism RD², similar to relays 1106 and 1108, are energized and hence negative 120 volt current will be connected to the conductor 448 and extended thereover through the left-hand winding of the differential relay 320 to ground. This momentary impulse will not be transmitted to the right-hand winding of differential relay 321 since the slow-to-release relay 319 is energized at this time. The operation of relay 320, in response to said impulse of current, opens the energizing circuit for relay 319, which, after an interval, releases but said relay does not close its contact until the current has been removed from the conductor 448. In energizing, relay 320 locks from grounded battery through its right-hand alternate contact and winding to ground at the alternate contact of relay 311. The operation of relay 320 also establishes a circuit for relay 322 extending from grounded battery through the right-hand alternate contact of relay 320, the right-hand contact of relay 323, the winding of relay 322 and the alternate contact of relay 311 to ground. Relay 322 energizes to close through its contact a locking circuit for itself in series with the winding of relay 323. Relay 323, however, does not energize at this time since the same is short-circuited by battery from the right-hand alternate contact of relay 320 which is connected through the contact of relay 322. The operation of relay 320 also establishes an energizing circuit for relay 324 extending from grounded battery through the winding of relay 324, the right-hand contact of relay 325, the left-hand normal contact of relay 323, the left-hand contact of relay 320 and the right-hand normal contact of relay 321 to ground. Relay 324 energizes and in so doing extends the ground connected to its left-hand contact through the left-hand normal contact of relay 325, the wipers 401 and 412 and the terminals engaged thereby, and the winding of relay 504' to grounded battery.

The relay 504' is associated with a switch W which is common to the lines of the group in which line L is located and which operates to engage the wipers 505 to 511 thereof with terminals individual to the selected line register. A number of these switches W are provided for the various groups of lines so that any of the line circuits associated with the lines extending to the selected toll center may be connected to the distributors SD¹ and RD¹ which are employed for transmitting to the inward office the code set up on a line register. A master switch X, which is common to all of the switches W, operates to select the switch W assigned to the group in which line L is located and when the wipers 512 to 518 of switch X engage the terminals to which the wipers of switch W are connected, the impulses of the code set up on

the line register are transmitted through the sending distributor SD¹ to the receiving distributor RD¹.

- Returning now to the operation of relay 504' in the circuit described therefor it will be seen that the closure of the left-hand contact of this relay establishes an obvious circuit to energize relay 519 of switch W. The closure of the right-hand contact of relay 504 connects ground to the terminal in the row over which wiper 505 passes, the said terminal being individual to the line L. The operation of relay 519 establishes an operating circuit for the stepping magnet 520 of switch W, said circuit being traceable from grounded battery through the winding and contact of magnet 520, the normal contact of relay 521, the left-hand alternate contact of relay 519 to ground. The operation of magnet 520 causes the wipers of switch W to be stepped until the terminal grounded by the operation of relay 504 is reached whereupon an obvious energizing circuit is established for relay 521. This relay, in operating, opens the circuit for the stepping magnet 520 and the wipers of switch W are therefore brought to rest upon the terminals individual to line L.
- At the time that relay 519 is energized to establish a stepping circuit for magnet 520, the operation of said relay also grounds, at its right-hand contact, the common conductor 522 to which are multiplied conductors extending to relays similar to relay 519 at the remaining switches W. The grounding of this common conductor closes an obvious stepping circuit for magnet 523 of switch X and this magnet thereupon operates the wipers of switch X to hunt for the terminals to which the wipers of switch W are connected. When relay 521 of switch W operates, the terminal in the row over which wiper 512 of switch X passes is grounded, and upon engagement of this wiper with said terminal a circuit is established to energize relay 524 of switch X. This relay opens its normal contact to break the stepping circuit for magnet 523 and switch X thereupon comes to rest upon the terminals to which the wipers of switch W are connected. The energization of relay 524 establishes a circuit for the start magnet 525 of sending distributor SD¹, which circuit is traceable from grounded battery through the ring 526, the brush arm 527, the start segment 528, contact of relay 529, the right-hand contact of relay 524 and the winding of magnet 525 to ground. Magnet 525 energizes to permit the brush arm 527 to revolve, during which time a code of impulses, individual to the inward position at which the group of lines including line L terminates at the distant office, are transmitted over the common signaling path P' to cause the receiving mechanism to se-

lect said position and the call indicator associated therewith. The polarities for this code of impulses are connected to conductors joined to the alternate contacts of relay 306 which was operated at the time 70 that relay 304 energized to remove the short circuit from relays 306 and 307.

At the beginning of the revolution of the brush arm 527 the same engages segment 530 to establish a circuit extending from 75 positive battery through segment 530, brush arm 527, ring 533, and from thence over one path by way of the lower winding of polar relay 532 and the artificial line to ground, and over another path through the upper 80 winding of polar relay 532, the common conductor P' and both windings of polar relay 800 and the artificial line to ground. This current being of positive polarity causes the polar relay 800 to close its upper contact 85 and thereby establish an operating circuit for the start magnet 801 of the distributor RD¹, said circuit being traceable from grounded battery through the upper contact of relay 800, the segment 802, brush arm 803, segment 804 and the winding of magnet 801 to ground. In operating, magnet 801 releases brush arm 803 so that the same will revolve in synchronism with the brush arm 527 of the sending distributor SD¹. 90 As soon as the brush arm 527 has passed over start segment 528 the same engages the segment 533 to establish a circuit extending from grounded battery through the ring 526, brush arm 527, segment 533 and the winding of relay 534 to ground. Relay 534 operates in this circuit to establish an energizing circuit for stepping magnet 535 of switch V, said circuit extending from grounded battery through the contact of relay 534, wipers 514 and 507 and terminals engaged thereby, and the winding of stepping magnet 535 to ground. This magnet energizes but the apparatus controlled thereby is so arranged that the operation of said stepping magnet does not move the wipers of switch V, the same being only stepped upon the release of said magnet. The brush arm 527 now successively engages segments 536, 537, 538 and 539 to 105 110 transmit over the conductor P' the polarities connected to the alternate contacts of relay 306. Through the polarities of these impulses certain of the locking relays 805 to 808 are operated. In accordance with 115 the present showing the polarities for the code individual to the selected inward position consist of positive, negative positive and negative impulses in the order named.

When brush arm 527 engages segment 536 120 125 the segments 809 and 810 are simultaneously engaged by the brush arm 803 of the receiver RD¹ and a circuit is thereupon established extending from positive pole of battery through the left-hand alternate contact of 130

relay 306, wipers 403 and 416 and terminals engaged thereby, the alternate contact of relay 308, which is operated at this time, wiper 541 of switch V and the normal terminal 5 engaged thereby, wipers 511 and 518 and the terminals engaged thereby, segment 536, brush arm 527, ring 531, the upper winding of polar relay 532, conductor P' and windings of relay 800 to ground. This impulse of current being of positive polarity the relay 800 will again close its upper contact and hence no circuit will be closed through segments 809 and 810 to operate relay 805. The brush arms of distributors SD⁴ and RD⁴ next engage, respectively, the segments 537 and 811. The next impulse is of negative polarity and is connected through the wipers 404 and 415 and terminals engaged thereby, the wipers 542, 510 and 517, segment 537, brush arm 527, ring 531, and from thence over the previously described path through the polar relays 532 and 800. This impulse of negative polarity causes relay 800 to close its lower contact 25 whereupon a circuit is established for locking relay 806 extending from grounded battery through the lower contact of relay 800, segment 809, brush arm 803, segment 811 and the right-hand winding of relay 806 to ground. Relay 806 operates and locks through its left-hand winding and contact to ground at the left-hand contact of relay 812, which was operated when the brush arm 803 first engaged segment 813, the circuit for relay 812 extending from grounded battery through the ring 814, brush arm 803, segment 813 and the winding of relay 812 to ground. The next impulse of positive polarity is transmitted through the outer right-hand alternate contact of relay 306, wipers 402 and 413 and terminals engaged thereby, the lowermost alternate contacts of the relays 600, 604, 608, 612, etc. in series, wipers 548, 509 and 516 and terminals engaged thereby, segment 538, and from thence over an obvious path through the windings of polar relays 532 and 800. This impulse of current causes the relay 800 to close its upper contact and since segment 815, which is now engaged by the brush arm, is not connected to said contact, locking relay 807 will fail to operate. The fourth impulse of negative polarity, which is transmitted at the time brush arms 527 and 803 are in engagement with segments 539 and 816, respectively, is connected through the inner right-hand alternate contact of relay 306, wipers 403 and 414 and terminals engaged thereby, the winding of relay 504, the middle alternate contacts of relays 600, 604, 608, 612, etc. in series, the wipers 544, 508, 515 and terminals engaged thereby, segment 589 and from thence over the common signaling path P'. Relay 800 responds to this impulse of current by closing its lower contact and thereby establishes a circuit extending from grounded battery through said contact, segment 809, brush arm 803, segment 816 and the right-hand winding of relay 808 to ground. Relay 808 energizes and locks 70 through its left-hand winding and contact to ground at the left-hand contact of relay 812. When the brush arm 527 passes from engagement with the segment 533 the circuit for relay 534 is opened and this relay releases to disconnect battery from the winding of the stepping magnet 535, which thereupon restores to step the wipers of switch V from their normal positions to position 2. The wipers 541 to 544 of switch V 75 are then associated with register relays 602, 603, 606, and 607. When brush arm 527 passes from segment 539 the same engages segment 540 and causes the transmission of an impulse of negative polarity over the common conductor P' to operate relay 800 to close its lower contact, but the closure of this contact has no effect since brush arm 803 has, at that time, passed from engagement 80 with segment 816. Brush arm 803 next engages segments 817 and 818 whereby an impulse of negative 120 volt battery is connected to said segments and through the normal contact of relay 819. The purpose of this impulse will presently be described. 85 When the brush arm 527 again engages the start segment 528, the previously described circuit for magnet 525 is again closed and said magnet is operated to permit the brush arm 527 to continue in its rotation whereby 90 the code of impulses set up on the line register may be transmitted. 95

Associated with the receiving mechanism are a plurality of groups of relays, one group including relays 820, 821 and 822, the second group, relays 823, 824 and 825, and a third group, relays 826, 827 and 828. Each of these groups is individual to an inward operator's position and to the call indicator at said position. Also included in the receiving apparatus is a group of pyramid relays 829 to 835 of a type well-known in the art and certain combinations of these relays are operated in accordance with the condition of the locking relays 805 to 808 to select the 100 position at which the group of lines, including line L, terminates. 110

When relay 806 operates, as previously described, a circuit is established extending from ground through the right-hand contact of said relay, the next to the innermost normal contacts of relays 828, 825 and 822 in series, and the windings of relays 831 and 830 to grounded battery. These latter relays operate in this circuit. After relay 808 115 is energized and when the 120 volt negative current is connected to segments 817 and 818 and the normal contact of relay 819, this current is extended through the right-hand alternate contact of relay 808, the out- 120

65 130

ermost normal contacts of relays 828, 825 and 822 in series, the lower normal contact of relay 829, the lower alternate contact of relay 831, the upper normal contact of relay 835 and the right-hand winding of the relay 900 to ground, the latter relay being individual to the operator's position at which the line L terminates. Relay 900 operates and is locked through its left-hand winding and 5 contact to ground at the inner normal contact of relay 901 with a result to be presently described. When the brush arm 803 passes from segments 813, 817 and 818, the holding 10 circuit for relay 812 is opened to cause the restoration of relays 806 and 808, and the 15 negative 120 volt battery is disconnected from the right-hand winding of relay 900. Relays 830 and 831 are restored by the release of relay 806. The brush arm 803 is 20 brought to rest by the armature of magnet 801 and now awaits the transmission of a code of impulses from the line register. At the time that the position relay 900 is operated, a circuit is established for relay 820 25 of the group of relays individual to the selected position, said circuit being traceable from grounded battery through the right-hand contact of relay 900 and the winding of relay 820 to ground. The operation of 30 relay 820 has no effect at this time except to prepare an energizing circuit for certain of the relays associated with the call indicator.

When brush arm 527 has completed its 35 operation and again engaged the start segment 528, start magnet 525 is again operated in the same manner, as previously described, to release the brush arm 527 to permit the same to revolve. When the brush arm 527 40 engages segment 530 the start magnet 801 of distributor RD¹ is operated, as before, to release the brush arm 803, which then starts to revolve in synchronism with the brush arm 527. At the beginning of its revolution 45 the brush arm establishes the previously described energizing circuit for relay 812. At the beginning of rotation of brush arm 527, the previously described circuit for relay 534 is closed to energize this relay, which in 50 turn energizes the stepping magnet 535, but, as previously, the wipers of switch V are not stepped until magnet 535 releases.

55 *Transmission of code impulses from line register to call indicator.*

The apparatus is now in condition to 60 transmit the eight sets of impulses comprising the code of the line which is being called and these impulses are transmitted in accordance with the condition of the register relays in Fig. 6. With the wipers of switch V in position 2 to which they were stepped by the release of the magnet 535 when relay 534 released near the termination of the

first revolution of the brush arm 527, the 65 register relays 602, 603, 606 and 607 are associated with the sending distributor SD¹. It will be recalled that of the register relays mentioned only relays 606 and 607 are energized. Therefore, the code for the first 70 series of the eight comprises two positive and two negative impulses transmitted in the order named. The first two positive polarities are connected through normal contacts of relays 602 and 603, and the next 75 two negative impulses through the right-hand alternate contacts of relays 606 and 607. The first positive impulse is transmitted when brush arm 527 engages segment 80 536, at which time brush arm 803 is in engagement with the segment 810. The circuit for the first positive impulse extends from the source of positive polarity through the normal contact of relay 603, the wiper 85 541 in position 2, the wipers 511 and 518, segment 536 and from thence over the previously described path through the windings of polar relays 532 and 800. This positive 90 impulse causes relay 800 to close its upper contact and hence no circuit will be established for the locking relay 805. Brush arm 527 next engages the segment 537, at which time brush arm 803 engages segment 811. The second positive impulse is transmitted 95 from the source through the normal contact of relay 602, wiper 542 in position 2, wipers 510 and 517, segment 537 and from thence through the windings of the polar 100 relays 532 and 800 to ground. This positive impulse again causes relay 800 to close its upper contact and hence no circuit will be established for relay 806. The next impulse 105 of the series is of negative polarity and the circuit therefore extends from the source of current through the right-hand alternate contact of relay 607, wiper 543 in position 2, wipers 509 and 516, segment 538 and from thence through the windings of the polar 110 relays 532 and 800. At this time wiper 803 is in engagement with segment 815 and when relay 800 closes its lower contact in response to the third impulse of current, relay 807 will operate and lock over an obvious circuit. Brush arms 527 and 803 next engage, 115 respectively, segments 539 and 816. The fourth impulse of the series is also of negative polarity and extends from the right-hand alternate contact of relay 606 through the wiper 544 in position 2, wipers 508 to 120 515, segment 539 and then through the windings of polar relays 532 and 800 to ground. The closure of the lower contact of relay 800, in response to this impulse, causes the operation and locking of relay 808. The brush arm 527 now disengages segment 533 with the result that the relay 534 releases 125 and in turn releases stepping magnet 535, whereupon the wipers of the switch V will

step to position 3 to associate wipers 541 to 544 with register relays 610, 611, 614 and 615.

- When relay 812 operated at the beginning 5 of the revolution of brush arm 803, a circuit for relays 821, 822 and 903 is established. This circuit extends from grounded battery through the right-hand contact of relay 812, the contact of relay 820, the normal contact of relay 904, and from thence by one path through the winding of relay 903 to ground, and by another path through the windings of relays 822 and 821 in series to ground at the lower contact of relay 915. 10 Relays 821, 822 and 903 operate in this circuit. The operation of relay 903 closes a circuit extending from ground through its winding and contact and from thence in parallel through the windings of relays 902 15 and 904 to grounded battery at the right-hand contact of relay 900, but as long as relay 812 is operated battery connected to the alternate contact of said relay short-circuits relays 902 and 904 through the normal 20 contact of relay 904 and the contact of relay 903. When relay 822 energizes the same connects contacts of locking relays 805 to 808 to normal contacts of the transfer relay 902. When relay 821 energizes a circuit is 25 established from ground through the left-hand contact of relay 821 and the winding of relay 819 to grounded battery. Relay 819 energizes to disconnect the segment 817 of the receiving distributor from the normal 30 contact of relay 819 so that when segments 817 and 828 are engaged by the brush arm 803 no negative 120 volt impulse will be transmitted through the normal contact of relay 819. 35 The relays 807 and 808 being operated by the first series of impulses transmitted, circuits are established for call indicator relays 1000 and 1001. The circuit for relay 1000 extends from ground through the right-hand contact of relay 807, the next to the outermost normal contacts of relays 828, and 825, the next to the outermost alternate contact of relay 822, the inner lower normal contact of relay 902 and the lower 40 winding of relay 1000 to grounded battery. Relay 1000 operates and locks through its upper winding and inner upper alternate contact to ground at the inner contact of relay 901. The circuit for relay 1001 extends from ground through the alternate contact of relay 819, which is energized at this time, the alternate contact of relay 808, the outermost normal contacts of relays 828 and 825, the outermost alternate contact of 45 relay 822, the outer lower normal contact of relay 902 and the lower winding of relay 1001 to grounded battery. Relay 1001 energizes and locks through its upper winding and upper alternate contact to ground at 50

the inner contact of relay 901. The relays 1000, 1001, 1002 and 1003 are individual to the lamps of the call indicator which are employed to designate the first letter of the office code. Similarly, relays 1004, 1005, 1006 and 1007 are assigned to the lamps 65 70 designating the second letter of the office code; relays 1008, 1009, 1010 and 1011 to lamps which indicate the third letter of the office code; and relays 1012, 1013, 1014 and 1015 to lamps which indicate the letters of the station designations. The relays and circuits therefor which are assigned to the numerical lamps have been omitted from the showing for the purpose of economy, but it is to be understood that these relays and circuits are similar in every respect to those of the office designations. To illustrate the manner in which circuits for these numerical lamps are established, two lamps 75 80 85 90 95 100 105 110 115 120 125 130 135 140 145 150 155 160 165 170 175 180 185 190 195 200 205 operation of relay 806. The relay 812 is also operated at the beginning of the revolution of brush arm 803 to establish a circuit for relay 906 extending from grounded battery through the right-hand contact of relay 812, the contact of relay 820, the alternate contact of relay 904, the normal contact of relay 907 and the winding of relay 906 to ground. Relay 906 energizes to close circuits through its winding and the windings of relays 905 and 907 in series to grounded battery at the right-hand contact of relay 900. However, while relay 812 is energized relays 905 and 907 are short-circuited through the normal contact of relay 907 and the contact of relay 906. The operation of relay 806 establishes a circuit for relay 1006 of the second group of office relays, said circuit being traceable from ground through the right-hand contact of relay 806, the next to the innermost normal contacts of relays 828 and 825, the next to the innermost alternate contact of relay 822, the inner upper alternate contact of relay 902, the inner upper normal contact of relay 905 and the lower winding of relay 1006 to grounded battery. Relay 1006 energizes and locks through its upper winding and inner upper alternate contact to ground at the inner contact of relay 901. At the termination of the revolution of brush arm 803, relays 812 and 806 are released and the restoration of the former removes the short-circuit for relays 905 and 907, whereupon these two relays energize in series with relay 906 to transfer the conductors from the locking relays to the normal contacts of relay 908. When brush arm 527 terminates its second revolution, relay 534 and stepping magnet 535 release and wipers of switch V are stepped to position 4.

The series of impulses for the third office designation is now transmitted. Register relays 618, 619, 622 and 623 control the polarities for this series. Of these relays only the relay 622 is energized. This relay controls the fourth impulse transmitted which is of negative polarity, the three preceding impulses being of positive polarity. The distributors SD¹ and RD¹ operate, as previously described, to transmit and receive the series of impulses for the third office designation with the result that relays 808 and 812 are energized, relay 808 being responsive to the fourth or negative impulse. The energization of relay 812, at the beginning of the revolution of brush arm 803, establishes a circuit for relay 909 through the alternate contacts of relays 904 and the normal contact of relay 910. Relay 909, in energizing, closes circuits in series with relays 908 and 910 but these latter relays are short-circuited, in the manner which is now believed to be understood, as long as relay 812 is energized. The operation of relay

808 establishes a circuit for the indicator relay 1009 extending from ground through the alternate contact of relay 819, the right-hand alternate contact of relay 808, the outermost normal contacts of relays 828 and 825, the outermost alternate contact of relay 822, the outer lower alternate contacts of relays 902 and 905, the outer lower normal contact of relay 908, and the lower winding of relay 1009 to grounded battery. Relay 1009 operates and locks through its upper winding and alternate contact to ground at the inner contact of relay 901. At the termination of the revolution of brush arm 803, relays 812 and 808 release and relays 908 and 910 energize in series with relay 909 to transfer the conductors to the normal contacts of a relay, similar to relay 908, associated with the group of indicator relays individual to the first numerical designation. Four series of impulses are now transmitted in accordance with the setting of the numerical relays (not shown) in the line register in the same manner that the series of impulses for the office designations were transmitted. During the transmission of these four series of impulses the wipers of switch V are stepped to position 8 in a manner which is now believed to be obvious. When the code for the last numerical designation has been transmitted, the wipers of switch V are stepped to position 9.

The last series of impulses corresponding to the station designation of the wanted line is now transmitted. This series of impulses is controlled by relays 626, 627, 630 and 631, of which relays 627 and 630 are energized. The code for this last series, therefore consists of negative, positive, positive and negative impulses in the order named. This code of impulses being received at the receiving distributor RD¹ causes the operation of relays 812, 805 and 808. The operation of relay 812 causes the operation of relay 914 over a circuit extending through the alternate contacts of relays 904, 907, 910 and 913 in series, and the winding of relay 914 to ground. It will be understood that relays 911, 912 and 913 have previously been energized by the transmission of a code of impulses for one of the numerical designations. The relay 916 is short-circuited through the contact of relay 915 as long as relay 812 remains operated. The operation of relays 805 and 808 establish circuits for the call indicator relays 1015 and 1013, respectively. Relay 1015 operates over a circuit traceable from ground through the right-hand contact of relay 805, the innermost normal contacts of relays 828 and 825, the innermost alternate contact of relay 822, the outer upper alternate contacts of relays 902, 905, 908 and 911 in series, and the lower winding of relay 1015 to grounded battery.

Relay 1015 operates and locks through its upper winding and lower alternate contact to ground at the inner contact of relay 901. The circuit for relay 1013 extends from ground through the alternate contact of relay 819, the right-hand alternate contact of relay 808, the outermost normal contacts of relays 828 and 825, the outermost alternate contact of relay 822, the outer lower alternate contacts of relays 902, 905, 908 and 911 in series, and the lower winding of relay 1013 to grounded battery. Relay 1013 operates and locks through its upper winding and alternate contact to ground at the inner contact of relay 901. At the termination of the last revolution of brush arm 803, relay 812 releases to remove the short-circuit for relay 916, which thereupon operates in series with relay 915. The restoration of relay 812 also releases relays 805 and 808. When the brush arm 527 of the distributor SD¹ engages the segment 533 during the last revolution of the distributor, relay 534 operates, as before described, to cause the energization of stepping magnet 535 preparatory to moving the wipers of switch B to normal position. With the wiper 545 now in position 9 a circuit is established for relay 546 extending from grounded battery through the contact of relay 534, the wipers 514, 507 and 545 and terminals engaged thereby, the normal contact of relay 547, the winding of relay 546 and the right-hand contact of relay 501 to ground. Relay 546 energizes and locks in a circuit extending from grounded battery through the winding of relay 547, the right-hand contact and winding of relay 546, and the right-hand contact of relay 501 to ground. Relay 547 does not energize in this circuit at this time since it is short-circuited by the battery connected to the contact of relay 534. When relay 534 releases after the brush arm 527 has passed from engagement with the segment 533, the short-circuit for relay 547 is removed and this relay then operates in series with the locking circuit of relay 546. The removal of battery from the contact of relay 534 also releases stepping magnet 535 and causes the same to step its wipers 541 to 543 to their normal positions where the same remain until again operated to transmit impulses from the line register for another call. The energization of relay 547 establishes a circuit extending from ground through the left-hand contacts of relays 547 and 546, the wipers 506 and 513 and terminals engaged thereby and the winding of relay 529 to grounded battery. Relay 529 energizes to permanently open the circuit for start magnet 525, which thereupon releases to stop the brush arm 527 at the termination of its revolution. The operation of relay 916, as previously described, opens at its lower normal contact, the holding circuits for relays 821 and 822, which thereupon restore to permit of the connection of the locking relays 805 to 808 to the pyramid position selecting relays 829 to 835, whereby another operator's position 70 and call indicator may be selected by the operation of distributors SD¹ and RD¹ in response to another call. The operation of relay 916 also removes ground at its lower 75 normal contact from the winding of relay 701, which relay thereupon releases. The release of relay 701 results in the transmission of a code of impulses from the incoming office to the outward office whereby apparatus in the latter office is operated to 80 release the line register and other associated mechanism. When relay 701 closes its right-hand contact, a circuit is established for relays 1139 and 712 in series, said circuit being traceable from grounded battery through the winding of relay 1139, the outer right-hand contact of relay 713, the winding of relay 712, the right-hand normal contact of relay 716, the right-hand contact of relay 717, which is energized at this time due to 90 a previous operation, the right-hand contact of relay 701, the continuity contacts of relay 720, and the normal contact of the supervisory relay 721 to ground. Relays 1139 and 712 energize in this circuit and the latter 95 relay locks through its winding and right-hand alternate contact to ground. The operation of relay 712 disconnects ground from its inner right-hand normal contact to open the locking circuit of relays 717 and 718, whereupon these relays release. The operation of relay 1139 has the same result as previously described, namely, to energize a relay in the sending mechanism SD², similar 100 to the relay 318, which controls the stepping of the switch U. This switch in the mechanism SD² is already connected to terminals of the line L by a previous operation. The energization of relay 712 establishes a circuit 105 extending from grounded battery through the left-hand winding of a relay in the mechanism SD², similar to the relay 429, through the wiper, similar to the wiper 421, in said mechanism, conductor 719, left-hand contact of relay 712, conductor 710, and from thence to ground through the winding of a relay in the mechanism SD², similar to 110 relay 446. The relay, similar to relay 429, energizes to establish an energizing circuit for the start magnet of the sending distributor SD², whereby a code of impulses for line L is transmitted over the common 115 signaling path P to the receiving mechanism RD² at the outward office. The relay 120 similar to relay 446 at mechanism SD², energizes in the circuit described therefor and thereby establishes a circuit for a relay, similar to relay 447, said circuit extending from ground through the contact of relay 446, the winding of the relay, similar to 125 130

relay 447, and the inner right-hand contact of the relay, similar to relay 429, to grounded battery. Relay 447 at mechanism SD² energizes and locks through its left-hand contact during the energization of relay 429. By closing its right-hand alternate contact the relay, similar to relay 447, connects negative potential to the segment 444 of the sending distributor at the mechanism SD² so that when the brush at said mechanism engages this segment the negative potential connected thereto will cause the polar relay 430 to close its lower contacts and thereby establish a circuit for the locking relay in the mechanism RD², similar to relay 1109. The operation of relay 1109 at the mechanism RD² connects positive 120 volt battery to the right-hand alternate contact of relay 1109 from whence this battery is extended to the signal receiving conductor 448 and through the left-hand winding of relay 320 to ground. At this time relay 319 is released due to the previous energization of relay 320, and the momentary impulse, through the conductor 448, will, therefore, also be extended through the contact of relay 319 and the right-hand winding of the differential relay 321. This impulse being of positive polarity will cause relay 320 to release and will operate relay 321, but this relay immediately releases since the current flowing through the locking winding opposes that through the right-hand winding. The momentary operation of relay 321 has no effect. At the termination of the transmission of the code of impulses from the mechanism SD² to the receiving mechanism at the outward office, the latter mechanism restored to normal in a manner which will be understood from the foregoing description of the mechanism RD. During the rotation of the sending distributor at SD² the relay, similar to relay 438 in said mechanism, is operated to energize relay 713 over conductor 1140, as previously described, whereupon the energizing and locking circuit for relays 712 and 1139 is opened and these relays release. Relay 712 is slow in releasing to allow ample time to obtain the results of the energization of relays in the mechanism SD², similar to relays 446 and 447. When the left-hand contact of relay 712 is opened the relay 446 of mechanism SD² releases but relay 447 remains operated in its locking circuit controlled by the relay 429 of the mechanism SD², which relay is not released until the brush arm of the sending distributor at SD² disengages the segment 437, thereby causing the release of relay 438. The release of the differential relay 320, as above described, permits relay 319 to again operate and removes the previously referred to short-circuit of relay 323 and this relay thereupon operates in series with the locking circuit of relay 322. When relay

320 opens its left-hand contact and relay 323 operates, the short-circuit for relay 325, produced by the ground at the normal contact of relay 321, is removed and relay 325 thereupon operates in series with the locking circuit of relay 324. The energization of relay 325 removes ground which is connected through the left-hand normal contact of said relay, from the winding of relay 504 and this latter relay thereupon restores. The removal of ground from the contacts of relay 504, when the same releases, causes the restoration of relays 519 and 521. The release of these relays opens the circuit for relay 524 and this relay thereupon releases. The wipers of switches W and X now remain in engagement with the terminals to which they were stepped until another register is selected and the relay 504 operated, whereupon one of the switches W and the switch X will again operate, as previously described. When relay 325 is energized relay 409 is short-circuited by ground connected to the alternate contact of relay 325, the right-hand alternate contact of relay 303, the wiper 400 and the alternate contact of relay 407. Relay 409 releases due to this short-circuit and in turn causes the release of relays 407 and 410 by the removal of ground from the left-hand contact of relay 409. The disconnection of ground from the right-hand contact of relay 409 permits the allotter switch S to again preselect the idle link Q. When relay 407 releases a circuit is established for stepping magnet 408 extending from grounded battery through the winding and contact of said magnet, the normal contact of relay 407, the wiper 400 and terminal engaged thereby, the right-hand alternate contact of relay 303, and the alternate contact of relay 325 to ground. The magnet 408 operates to step the wipers of switch O to the next position, and if the relays, similar to relay 303 of other lines, are released, switch O will continue to step until the normal positions of the wipers thereof are reached.

The release of relay 410 removes ground from the winding of relay 417 and this relay thereupon restores to remove ground from the multiple terminal engaged by the wiper 411. The wipers of switch R now remain in contact with the terminals engaged thereby until another switch, similar to switch R, has selected the line register shown in Fig. 6, whereupon the relay 417 of said other switch will operate to ground the multiple terminal engaged by the wiper 411, whereupon stepping magnet 418 will operate to step the wipers of switch R to the next succeeding terminals. This operation will continue until the wipers of switch R reach their normal positions whereupon the operation of this switch will

be the same as previously described. When wiper 411 steps from the terminal individual to the line register shown in Fig. 6, the windings of relay 500 are differentially connected and this relay is thereby caused to release, in turn releasing relay 501. This latter relay, after an interval, opens its contact whereupon relay 503 and all of the relays of the line register, which have been operated and locked to ground at the right-hand contact of relay 501 restore. The release of relay 501 also opens the locking circuit for relays 546 and 547 and these relays thereupon release. The line register is now in condition for another operation.

Returning to the operation of the relay 916, it will be seen that when this relay closes its alternate contact a circuit is established for relays 926, 917 and 918, extending from grounded battery through the windings of these relays in series and the alternate contact of relay 916 to ground. These relays energize to close circuits for the various call indicator lamps to be lighted. With relays 1000 and 1001 of the group assigned to the lamps which indicate the first office designation operated, a circuit is established for the lamp WXY extending from grounded battery through the inner left-hand contact of relay 916, the lamp WXY, the lower alternate contact of relay 1000, the upper normal contact of relay 1003, the lower normal contact of relay 1002, the upper alternate contact of relay 1001, and the inner contact of relay 901 to ground. The lamp WXY is lighted in this circuit. In the second group of relays, relay 1006 is operated. The energization of relay 926, therefore, closes a circuit to light lamp ABC, which circuit extends from grounded battery through the outer right-hand contact of relay 926, the lower normal contact of relay 1006, the lower alternate contact of relay 1006, the middle normal contact of relay 1007, lamp ABC, the upper alternate contact of relay 1006, the lower normal contact of relay 1007, the upper normal contact of relay 1004, and the inner right-hand contact of relay 926 to ground. In the third group representing the last office designation, relay 1009 is operated. Upon the energization of relay 917 a circuit is, therefore, established to light the lamp JKL, said circuit extending from grounded battery through the inner left-hand contact of relay 917, the lamp JKL, the lower normal contact of relay 1008, the upper normal contact of relay 1011, the lower normal contact of relay 1010, the upper alternate contact of relay 1009, and the inner contact of relay 901 to ground. The energization of relay 918 establishes a circuit to light the lamp M, representing the station designation, said circuit being traceable from grounded battery through the right-hand contact of relay 918, the lower

alternate contact of relay 1013, lamp M, the upper alternate contact of relay 1015, the normal contact of relay 1014, the upper alternate contact of relay 1013, and the inner contact of relay 901 to ground. The energization of relays 917 and 918 and another similar relay (not shown) control the lighting of the four lamps, representing the numerical digits of the wanted line. The eight lamps indicating the office number and station designations of the called line are now lighted before the incoming operator.

It will be obvious that if the called subscriber is not on a party line none of the last group of register relays 626, 627, 630 and 631 will be operated, and, therefore, the four impulses of the eighth series transmitted to the receiving distributor RD¹ will be of positive polarity, and none of the relays 805 to 808 will be operated, with the result that none of the relays 1012 to 1015 will be energized. The transfer relays 916 and 915 will, nevertheless, be operated in the same manner as previously described so that upon the energization of relay 916 the circuits for the office and number lamps will be closed to light these lamps.

Connection of toll switching trunk H to called subscriber's line.

The incoming operator, upon observing the number of the wanted line, communicates with the toll switching trunk operator over an order wire (not shown) to secure an assignment of a toll switching trunk. The toll switching operator then informs the incoming operator that the toll switching trunk H should be employed for extending the connection to the subscriber's line circuit J. The incoming operator also informs the toll switching operator the number of the wanted line whereupon the latter operator inserts the plug 722 of the toll switching trunk H into jack 723 of the called line. A circuit is thereupon established extending from grounded battery through the winding of relay 724, sleeve contacts of plug 722 and jack 723, and the winding of cut-off relay 725 to ground. Relays 724 and 725 operate in this circuit. The energization of the latter relay disconnects the line relay 726 from the subscriber's line circuit J so that said line relay will not operate upon response of the called subscriber, and will, therefore, prevent the lighting of the lamp of the line signal 727. The energization of relay 724 establishes a circuit for lighting the lamp 728 extending from grounded battery through the lamp 728, the right-hand alternate contact of relay 724, resistance 729, and the normal contact of relay 730 to ground. The energization of relay 724 also disconnects the usual operator's telephone circuit testing equipment from the tip conductor of the trunk circuit with which a test is made

by placing such tip conductor in contact with the sleeve of the jack 723 prior to the insertion of the plug 722. The closure of the left-hand alternate contact of relay 724 completes the continuity of the tip conductor.

Incoming operator connects toll line L to the toll switching trunk circuit H.

The incoming operator now inserts plug 731 into jack 732 whereupon a circuit is established extending from grounded battery through the winding of relay 733 and the sleeve contacts of plug 731 and jack 732 to ground. The energization of relay 733 in this circuit establishes a circuit extending from ground through the contact of relay 733, the left-hand contact of relay 709, and the winding of relay 901 to grounded battery. The relay 901 operates and in so doing removes ground from the locking circuits of the transfer relays 902 to 915 and also from the relays 1000, 1001, 1006, 1009, 1013 and 1015 with the result that all of these relays are restored to normal. When relay 901 opens its inner contact it also breaks the locking circuit for the position relay 900, which thereupon restores. The opening of the outer contact of relay 901 removes battery from the locking circuit of relay 709 and this relay thereupon releases to open the energizing circuit for relay 901. The latter relay releases but, being slow, remains operated sufficiently long to permit of the release of the relays of the indicator. The call indicator is now in its normal condition and ready for another operation.

The operation of relay 733 also closes an obvious energizing circuit for relay 707 which, in opening its lower normal contact, opens the circuit for guard lamp 706, which is thereupon extinguished. Lamp 711 may be extinguished by the operation of relay 707 or by the restoration of the assignment key 708 by the incoming operator at the time she receives the assignment of the toll switching trunk H and plugs into jack 732. The energization of relay 707 also disconnects the operator's testing equipment from the line and completes the continuity of the tip conductor. When relay 707 operates a circuit is established extending from grounded battery through the left-hand winding of relay 730, the continuity contacts of relay 734, the upper left-hand winding of repeating coil 735, the tip contacts of jack 732 and plug 731, the upper alternate contact of relay 707, the upper normal contact of relay 736, the upper right-hand winding of the repeating coil 737, the winding of the supervisory relay 721, the left-hand contact of relay 702, the lower right-hand winding of the repeating coil 737, the lower normal contact of relay 736, the ring contacts of plug 731 and jack 732, the lower left-hand winding of the

repeating coil 735, the inner left-hand normal contact of relay 734, and the right-hand winding of relay 730 to ground. Relays 721 and 730 operate in this circuit and the energization of the latter relay extinguishes the guard lamp 728.

The operation of supervisory relay 721 establishes an energizing circuit for the slow to operate and release relay 720, said circuit extending from grounded battery through the winding of relay 720 and the alternate contact of relay 721 to ground. A circuit is also established for relay 714 by the energization of relay 721, said circuit being traceable from grounded battery through the winding and right-hand continuity contacts of relay 714, the left-hand contact of relay 713, the outer right-hand normal contact of relay 712, the left-hand normal contact of relay 701, and from thence over the energizing circuit for relay 720. Relay 714 being slow to operate, a circuit will also be established for relay 716, before the left-hand continuity contacts of relay 714 are opened. The circuit for relay 716 extends from grounded battery through the winding of relay 1139, the inner right-hand contact of relay 713, the winding and continuity contacts of relay 716, the left-hand continuity contacts of relay 714, and thence over the energizing circuit for relay 714. Relay 716 locks through its right-hand alternate contact while the relay 714 locks through its right-hand alternate contact, the normal contact of relay 715, the outer normal contact of relay 712, and from thence over the energizing circuit for relay 714. As previously described, the closure of the inner left-hand contact of relay 716 causes the energization of relay 718 which prepares a circuit for relay 717, the latter relay operating when relay 716 releases.

Relay 1139 operates in the circuit described for relay 716 to initiate the operation of the sending mechanism SD² in the same manner as previously described, whereupon the same code of impulses is transmitted over the common signaling path P to effect the operation of the receiving distributor mechanism RD² at the outward office. This code of impulses causes negative 120 volt current to be momentarily connected to the conductor 448 and extended through the left-hand winding of relay 320 to energize this relay, whereupon the same is locked, as previously described. At the time this impulse was transmitted to relay 320, relay 319 is energized due to the previous release of relay 320 and relay 321 will be unaffected by this impulse. The energization of relay 320 establishes a circuit extending from ground through the normal contact of relay 321, the left-hand contact of relay 320, the alternate contact of relay 323, which

is energized at this time, the inner right-hand alternate contact of relay 307, the outer contact of relay 305, the resistance 308, and from thence over the previously described 5 circuit through the winding of marginal relay 202. This relay now energizes due to the inclusion of the resistance 306 in multiple with the winding of relay 301 and thereby establishes a circuit extending from 10 ground through the contact of relay 202, the right-hand alternate contact of relay 206, and the guard lamp 222 to grounded battery. The lamp 222 is lighted to indicate to the outward operator that the toll line L has 15 been extended to the called subscriber's line and that she may actuate her ringing key 221.

At the time the sending distributor SD² is transmitting the code of impulses to the 20 outward office, relay 713 is again operated in the same manner as previously described to open the locking circuit for relay 716, which relay then releases. Relay 714, however, remains energized. The removal of 25 ground from the inner left-hand contact of relay 716 permits relay 717 to operate in series with relay 718, but the operation of relay 717 at this time performs no function.

30 *The outward operator actuates the ringing key in the cord circuit A.*

The outward operator, upon observing the lighted condition of lamp 222, actuates the ringing key 221 and thereby connects ringing current from a suitable source through the lower alternate contact of key 221, the ring contacts of plug 203 and jack 300, the inner left-hand alternate contact of relay 307, the lower left-hand winding of repeating coil 326, condenser 327, winding of relay 328, the upper left-hand winding of repeating coil 326, the outer left-hand alternate contact of relay 307, tip contacts of jack 300 and plug 203, the alternate contact of 40 relay 204, the outer normal contact of relay 207, and the upper alternate contact of key 221 to ground. Relay 328 energizes in this 45 circuit to establish an obvious operating circuit for relay 317. The operation of the 50 latter relay causes the energization of relay 312 over a circuit extending from grounded battery through the right-hand contact of relay 313, the winding of relay 312, the alternate contact of relay 317, and the alternate contact of relay 311 to ground. Relay 312 operates in this circuit and locks 55 through its inner left-hand contact. When the outward operator releases the key 221, relay 328 releases in turn releasing relay 317. 60 The operation of relay 312 and release of relay 317 initiates, in the same manner as previously described, the operation of the sending mechanism including the switch U and the sending distributor SD. If, since

the last operation of the sending distributor 65 SD, the switch U had been operated by the seizure of another toll line, said switch will again be stepped to the terminals individual to line L by the energization of relay 318 in response to the operation of relay 312 and 70 release of relay 317. The wipers of switch U will be brought to rest upon the terminals individual to the line L, in the same manner as previously described, and the code of impulses for said line will thereupon be transmitted to the receiving distributor RD. As 75 before, the negative 120 volt current will then be momentarily connected to the conductor 700 and this impulse of current will be extended to ground through the right-hand winding of the differential relay 703 to energize this relay. This impulse of current is also passed through the left-hand winding of relay 702 but has no effect upon this relay since the same is already energized and locked. Upon energizing, relay 703 locks in a circuit extending from grounded battery through its left-hand winding and contact and the contact of relay 704 to ground. The opening of the normal contact 80 of relay 703 opens the energizing circuit for relay 704, but the latter relay is very slow in releasing and, therefore, will maintain its contact closed for an appreciable interval. The operation of relay 703 establishes a circuit for the slow-to-operate and 85 release relay 705, said circuit extending from ground through the winding of relay 705, the right-hand alternate contacts of relays 703 and 702 to grounded battery. Relay 705 energizes after which the contact of relay 704 opens and relay 703 releases. The release of relay 703 opens the energizing circuit for relay 705, but this relay being slow-to-release will maintain its contacts closed 90 for an interval after its energizing circuit is opened. The operation of relay 705 causes the energization of slow-to-release relay 738 over an obvious circuit and the latter in turn closes an obvious operating circuit for the slow to release relay 739. The operation of relay 738 also establishes an energizing circuit for the ringing relay 736, whereupon 95 this relay energizes. Due to the slow release nature of relays 705 and 738, relay 736 will be maintained operated for an appreciable length of time after the release of relay 703. During the operation of relay 100 736, a circuit is completed from the source of ringing current through the lower alternate contact of relay 736, the ring contacts of plug 731 and jack 732, the lower left-hand winding of repeating coil 735, the winding of the ringing response relay 740, condenser 741, the upper left-hand winding 105 of the repeating coil 735, tip contacts of jack 732 and plug 731, and the upper alternate contacts of relays 707 and 736 to ground.

Relay 740 operates in this circuit to establish an energizing circuit for the ringing relay 742, said circuit being traceable from ground through the contact of relay 740, 5 winding of relay 742, and the left-hand winding of relay 734 to grounded battery. Relays 734 and 742 operate in this circuit and the energization of the former opens the original energizing circuit for relay 730, but 10 this relay is maintained energized through the alternate contact of relay 734. The operation of relay 742 closes a circuit extending from the source of ringing current through the upper alternate contact of said 15 relay, the ring contacts of plug 722 and jack 723, the substation apparatus at J, the tip contacts of jack 723 and plug 722, the left-hand alternate contact of relay 724, and the lower alternate contact of relay 742 to 20 ground. The called subscriber's bell is operated in this circuit to signal the subscriber that a call is to be answered.

During the operation of relay 736, the circuit for relay 721, through the normal contacts of relay 736, is opened and relay 721 releases. In so doing, the locking circuit for relay 714 is opened and this relay restores. As soon as relays 705 and 738 are restored to normal, relay 736 releases to disconnect the ringing current from relay 740, which thereupon releases, in turn releasing relay 742, to prevent further application of ringing current to the called line. When relay 734 restores, in response to the removal of ground from the contact of relay 740, relays 730 and 721 are again energized over the original circuit described therefor. The operation of relay 721 again causes the original energizing circuit for relay 720 to 30 maintain this relay in its operated condition, it having been held operated during the release of relay 721 by the energization of relay 739. Relay 720, being slow to release, the interval between the release of relay 739 and the energization of relay 721 is not sufficient to permit of the release of relay 720. While the supervisory relay 721 is released during ringing and relay 720 is operated, a circuit is established for the slow release relay 743 extending from grounded battery through the winding of relay 743, the alternate contact of relay 720, and the normal contact of relay 721 to ground. Relay 743 energizes but its operation has no effect upon the system at this time. The foregoing operation, in response to the actuation of the ringing key 221, is repeated each time said key is depressed to operate the called subscriber's bell.

60 *Subscriber at substation J removes the receiver from its switch hook.*

In response to the operation of the signal at the called substation, the subscriber 65 thereat removes his receiver from its switch

hook, thereby establishing a circuit for the supervisory relay 744 extending from grounded battery through the winding of relay 744, the upper right-hand winding of the repeating coil 735, the upper normal contact of relay 742, the ring contacts of plugs 722 and jack 723, substation apparatus, the tip contacts of jacks 723 and plug 722, the left-hand alternate contact of relay 724, the lower normal contact of relay 742, and the lower right-hand winding of repeating coil 735 to ground. Relay 744 operates and thereby establishes a circuit for relay 734 extending from grounded battery through the left-hand winding of relay 734, the contact of relay 744, the right-hand winding of relay 734, and the alternate contact of relay 730 to ground. Relay 734 operates to again maintain the energization of relay 730 but in its operation opens the circuit for the supervisory relay 721, which thereupon releases. The relay 739 having released at this time, the opening of the alternate contact of relay 721 permanently opens the circuit for relay 720, which, after an interval, opens its alternate contacts and closes its continuity contacts. The previously described circuit for relays 1139 and 712, through the contacts of relays 713, 716, 717, 701, 720 and 721, is thereupon established and said relays energize to again effect the transmission of a code of impulses from the sending mechanism SD² to the receiving mechanism RD², in the same manner as previously described. It will be recalled that the code transmitted when relay 712 is operated contains a final impulse of negative polarity which causes the energization of a relay in the mechanism RD² similar to relay 1109. This connects positive 120 volt battery to the conductor 448 and this current, passing through the left-hand winding of relay 320, causes the same to release. The opening of the left-hand contact of relay 320 breaks the circuit through the resistance 308 and winding of marginal relay 202, whereupon this relay releases to open the circuit for lamp 222. The lamp 222 is extinguished to inform the outward operator that the called subscriber has answered and the operator will, therefore, no longer actuate the ringing key. When relay 712 is operated the circuit for relays 717 and 718 is opened at the inner right-hand normal contact of relay 712, and relays 717 and 718 thereupon release. During the rotation of the sending distributor of the mechanism SD², relay 713 is operated, as previously described, to open the energizing and locking circuit for relay 712, which relay thereupon restores. The restoration of the differential relay 320, in response to the impulse of positive polarity, again establishes a circuit for relay 319 to disconnect the right-hand winding of relay 321 from the conductor 448.

Toll switching operator inserts the plug of toll switching trunk H into a busy flash jack.

5 If at the time the toll switching operator tests line J, before inserting the plug 722 into jack 723, and finds the line busy, she then inserts said plug into a busy flash jack (not shown) which may be of any construction well-known in the art. Insertion of the plug into this jack connects ground through an interrupter, the ring contacts of said jack and plug 722, the upper normal contact of relay 742, the upper right-hand 15 winding of repeating coil 735, and the winding of the supervisory relay 744 to grounded battery. The operation of relay 744, in response to the action of the interrupter, produces the same effect as described in the 20 operation of this relay when the subscriber at substation J removed his receiver from its switch hook. The result of this operation is the transmission of a code of impulses to the receiving mechanism at the 25 outward office which causes the relay 320 to release, it being energized at this time, and the lamp 222 to be extinguished. It will be recalled that in this operation the supervisory relay 721 releases. When the supervisory relay 744 releases in response to the removal of ground from the relay 744 as the interrupter in the busy flash jack rotates, relay 734 releases and again closes a circuit for the supervisory relay 721 in series with the relay 730. The operation of relay 721 establishes the previously described circuit for relays 1139 and 716 through contacts of relays 713, 714, 712, 701 and 721 to energize relays 1139 and 716 in parallel with the relay 720. Relay 714 also energizes and locks, as previously described. The energization of relay 716 causes relay 718 to operate and prepare a circuit for relay 717 so that this latter relay will operate upon the energization of relay 713, as previously described, which results in the de-energization of relay 716, relay 714, however, remaining in its locked condition. The energization of relays 1139 and 716 results in the transmission of a code of impulses to the outward office in the same manner as previously described, whereupon an impulse of negative polarity will be connected to the conductor 448 to again operate relay 320. Lamp 222 is thereupon lighted and relay 319 is released. When relay 716 releases in response to the energization of relay 713 during the transmission of the code of impulses to light the lamp 222, relay 717 operates and this relay, together with relay 718, remains operated through the left-hand normal contact of relay 712.

When the interrupter in the busy flash jack next causes supervisory relay 744 to again operate, relay 721 releases to cause the restoration of relay 714. Relay 720, however, remains operated due to its slow release nature. Upon the next operation of relay 721, relays 714, 716 and 1139 again operate, as previously described, and the energization of relay 716 then establishes a circuit for relay 715 extending from grounded battery through the left-hand alternate contact of relay 702, the winding and continuity contacts of relay 715, the left-hand alternate contact of relay 717, and the inner left-hand contact of relay 716 to ground. Relay 715 energizes and locks through its winding and inner alternate contact and the inner normal contact of relay 712 to ground. The energization of relay 715 establishes a locking circuit for relay 714 extending through the winding and right-hand alternate contact of relay 714, the middle alternate contact of relay 715, and from thence to ground over the locking circuit of the latter relay. The maintenance of relay 714, in its operated position, prevents any further operation of the relay 716 in response to subsequent operations of relay 721 while the plug 722 is inserted in the busy flash jack. The second operation of relays 1139 and 716 causes the transmission of another code of impulses similar to the first code to the outward office. The impulse of negative polarity is connected to the conductor 448 and extended through the left-hand winding of relay 320 to ground. This relay is already energized and, therefore, this impulse has no effect thereupon. The momentary impulse is also extended through the contact of relay 319, which is now released, and the right-hand winding of relay 321 to ground. This negative impulse causes the relay 321 to energize and lock in a circuit extending from grounded battery through the left-hand contact and winding of relay 321, and the alternate contact of relay 311 to ground. The energization of relay 321 connects the busy back interrupter 329 to the circuit including the resistance 308 and marginal relay 202, and causes said relay to repeatedly operate and release whereby the lamp 222 is intermittently flashed. The flashing of this lamp serves to indicate to the outward operator that the line requires supervision and upon connecting her head set to the cord circuit A she will receive an audible busy signal.

Outward operator releases connection.

The outward operator then proceeds to release the connection by removing the plug 203 from the jack 300. This causes the release of relay 201 followed by the deenergization of relays 204, 205 and 206, thus restoring the cord circuit to its normal condition.

Relays 301 and 302 are also released by the removal of plug 203 from jack 300. The release of relay 301 opens the holding circuit for relay 303, which thereupon restores. The opening of the left-hand alternate contact of relay 303 removes ground from the locking circuit of relays 305, 306, 307, 324 and 325, and these relays thereupon restore. When relay 307 releases, ground is disconnected from the outer right-hand alternate contact of this relay to cause the release of relay 311. The removal of ground from the alternate contact of the latter relay opens the locking circuit for relays 320, 321, 322 and 323, and these relays thereupon release. The restoration of relay 311 also causes the release of relay 319. The relay 315 is now the only relay in the line circuit apparatus which is energized, this relay having been locked through its inner alternate contact and winding to ground at the left-hand normal contact of relay 314. When the normal contact of relay 311 is closed a circuit is, therefore, established for relay 314 extending from ground through the normal contact of relay 311, the middle contacts of relay 315, the winding of relay 314, and the left-hand normal contact of relay 313 to grounded battery. Relay 314 energizes and locks through its winding and left-hand alternate contact, and in opening its left-hand normal contact causes the restoration of relay 315. When relay 314 energizes a circuit is established for relay 318 extending from grounded battery through the winding of relay 318, the inner normal contact of relay 317, and the outer right-hand alternate contact of relay 314 to ground. The energization of relay 314 also connects ground to the terminal of switch U, which is individual to the toll line L and over which wiper 421 passes, said ground extending through the winding of relay 446, the inner right-hand alternate contact of relay 314 and the outer normal contact of relay 317. Assuming that the sending distributor SD has been employed with other toll lines since the transmission of the last code of impulses therefrom, the energization of relay 318 again causes the stepping magnet 428 to operate, as previously described, to step the wipers of switch U over the terminals until the wiper 421 engages the associated terminal individual to toll line L. Ground which is now connected to this terminal will be extended through the wiper 421, and the left-hand winding of relay 429 to grounded battery. Relays 429 and 446 now operate. The energization of relay 429 causes the wipers of switch U to come to rest on the terminals individual to line L and also closes the previously described circuit for start magnet 431. The operation of relay 446 establishes the pre-

ously described energizing circuit for relay 447 and this relay locks as before. The closure of the right-hand alternate contact of relay 447 connects battery of negative polarity to the segment 444 of the sending distributor SD, which now operates to transmit a code of impulses to the receiving mechanism at the inward office. While the distributor is revolving, relay 438 operates to energize relay 313, as previously described, whereupon the locking circuit for relay 314 is opened and this relay restores. Relay 313 releases in response to the restoration of relay 438 when the brush arm 433 disengages the segment 437. When relay 314 releases relay 318 also releases. The release of relay 438 opens the holding circuit for relay 429, which thereupon restores. The apparatus of Figs. 3 and 4 is now in normal condition and ready for another operation. 85

The code of impulses transmitted by the last operation of distributor SD is the same as that described in connection with the code of impulses from the mechanism SD² when the relay, similar to relay 447 therein, is operated, and upon this code of impulses being received by the receiving distributor RD, relays 1106, 1108 and 1109 are operated in a manner which is now believed to be obvious. The operation of these three relays, together with the energization of pyramid relays 1112 and 1113, causes the momentary impulse of positive 120 volt current to be connected to the conductor 700 and from thence through the left-hand winding of relay 702 to ground. Relay 702 is released by this impulse of positive polarity. The removal of battery from the right-hand alternate contact of relay 702 opens the locking circuits of relays 715, 717 and 718, and these relays thereupon restore. The opening of the left-hand contact of relay 702 permanently opens the energizing circuit of relay 721, which releases to open the locking circuit of relay 714. The release of relay 721 also opens the energizing circuit for relay 720, which then releases. 95

By the release of relay 702 and consequent deenergization of relay 721, guard lamps 706 and 728 are simultaneously lighted to give the inward and toll switching operators the disconnect signal. The lamp 706 is lighted over a circuit extending from grounded battery through the normal contact of relay 702, the lower alternate contact of relay 707, and the lamp 706 to ground. When relay 721 releases, relay 730 also restores and the previously described lighting circuit for lamp 728, through resistance 729, is thereupon established. 105

In response to the lighting of lamp 706 the inward operator removes the plug 371 from the jack 732 and thereby causes the re- 110

lease of relay 733 which removes ground from the winding of relay 707 and restores this relay to normal. The release of relay 707 opens the circuit for lamp 706 and this lamp is then extinguished.

The toll switching operator, observing the lighted condition of lamp 728, removes the plug 722 from jack 723 to release relays 724 and 725. The restoration of relay 724 10 opens the circuit for lamp 728, which is thereupon extinguished. The apparatus of the toll switching trunk is now in its normal condition.

15 *Subscriber at substation J after answering a call recalls the outward operator.*

Should the subscriber at substation J after removing his receiver from its switch hook desire to converse with the outward 20 operator, he may signal this operator by repeatedly depressing and releasing the switch hook. The supervisory relay 744 responds to this operation of the switch hook in the same manner as described in connection with the insertion of plug 722 in the 25 busy flash jack. Relay 721 also operates in the same manner as described in this connection and this again results in the two operations of relay 716, whereby two codes 30 of impulses are transmitted to the outward office to operate in succession the relays 320 and 321 which results in the flashing of the lamp 222.

Should the subscriber, after repeatedly 35 working his switch hook up and down, keep the receiver off the switch hook, the supervisory relay 744 will remain operated and the supervisory relay 721 will release. During the operation of the switch hook relay 40 720 is operated to establish the previously described circuit for relay 743 during the normal contact of relay 721. Upon the permanent restoration of relay 721 when the subscriber stops operating the switch hook, 45 the circuit for relay 720 is opened and this relay, after an interval, releases to open the energizing circuit of relay 743. When relay 743 restores a circuit is established for relay 712 extending from grounded battery 50 through the winding of relay 1139, the outer right-hand contact of relay 713, the winding of relay 712, the right-hand normal contact of relay 716, the right-hand contact of relay 717, which is energized at this time, 55 the right-hand contact of relay 701, the outer alternate contact of relay 715, which energized after the first operation of relay 716, and the continuity contacts of relay 743 to ground. Relay 712 energizes and locks, 60 as previously described, and the operation of this relay opens the circuits of relays 715, 717 and 718, which relays thereupon release. In the same manner as formerly described, the operation of relay 712 causes

the transmission of a code of impulses to 65 the receiving mechanism at the outward office which results in the connection of a positive impulse to the conductor 448. Relays 320 and 321 both being energized at this time this positive impulse, through the 70 left- and right-hand windings thereof, respectively, causes the same to release and thereby disconnect the interrupter 329 from the circuit including relay 202. The lamp 222 is thereupon extinguished. While this 75 lamp is flashing the outward operator, in response thereto, may supervise the connection by connecting her head set to the cord circuit A whereupon she may converse with the called subscriber.

After repeatedly operating the switch hook should the subscriber at substation J then replace the receiver upon its switch hook, a code of impulses following those 80 which caused the flashing and extinguishment of lamp 222 will be transmitted to the outward office to again light this lamp to give the outward operator the disconnect signal. When the receiver is replaced at substation J relay 744 releases to cause the 85 energization of relay 721. Relays 1139, 714 and 716 are thereupon operated, as previously described, to effect the transmission of the code of impulses to the outward office 90 which results in the connection of an impulse of negative polarity to the conductor 448. When relays 320 and 321 released in response to the positive impulse transmitted over the conductor 448 when relay 712 energized, relay 319 again operated to disconnect the relay 321 from the conductor 448. Therefore, when this last negative impulse is 95 transmitted over the conductor 448, only relay 320 will respond thereto. The energization of this latter relay again causes the 100 lamp 222 to be lighted and the outward operator, observing the condition of the lamp, removes the plug 203 from jack 300 with the previously described results. The disconnect signal is transmitted to the outward operator in the manner which will now be understood when the subscriber at substation J replaces his receiver upon its switch hook 105 upon the termination of the conversation.

When supervisory relay 721 operated in response to the replacing of the receiver upon its switch hook to cause the energization of relay 716, relay 718 operated, and when relay 716 released due to the energization of relay 713, relay 717 operated. Relays 714, 717 and 718, therefore, remain energized until the code of impulses is transmitted from the sending distributor SD to connect positive current to the conductor 700 which results in the release of relay 721. Relays 714, 717 and 718 will then restore to 115 normal.

This application is related to applicant's copending application Serial No. 492,229 filed Aug. 15, 1921.

What is claimed is:

- 5 1. In a telephone system, distant offices, a plurality of transmission lines interconnecting said offices, outward operators' positions at one of said offices, means under the control of said positions and operable to 70
10 automatically select an idle one of said transmission lines, means to indicate such line to an outward operator, signaling paths common to said transmission lines, a signal and a call indicator at one of said offices, 75
15 and means responsive to the seizure of said idle line by the outward operator for transmitting series of impulses over said signaling paths to operate said signal and said call indicator. 80
20 2. In a telephone system, distant offices, a plurality of transmission lines interconnecting said offices, outward operators' positions at one of said offices, means under the control of said positions and operable to 85
25 automatically select an idle one of said transmission lines, means to indicate such line to an outward operator, signaling paths common to said transmission lines, a signal and a call indicator at one of said offices, 90
30 and means for transmitting a series of impulses over one of said paths for initially operating said signal, and means for thereafter transmitting over said path other series of impulses for operating said call indicator. 95
35 3. In a telephone system, distant offices, a plurality of transmission lines interconnecting said offices, outward operators' positions at one of said offices, means under the control of said positions and operable to 100
40 automatically select an idle one of said transmission lines, means to indicate such line to an outward operator, signaling paths common to said transmission lines, signals at said distant offices, a call indicator at one of said offices, means for transmitting series of impulses over one of said paths for operating the signals at said offices, and means for transmitting other series of impulses over a different signaling path for operating said call indicator. 105
45
50 4. In a telephone system, distant offices, a plurality of transmission lines interconnecting said offices, outward operators' positions at one of said offices, means under the control of said positions and operable to 110
55 automatically select an idle one of said transmission lines, means to indicate such line to an outward operator, signaling paths common to said transmission lines, signals at said distant offices, a call indicator at one of said offices, means for initially transmitting a series of impulses over one of said paths for operating the signal at one of said offices, and means for thereafter transmitting other series of impulses modified with respect to the first series of impulses and to each other for operating said call indicator. 115
60
65 5. In a telephone system, distant offices, a plurality of transmission lines interconnecting said offices, groups of operators' positions at one office, means responsive to the initiation of a call by an operator at any of said operators' positions for selecting an idle one of said lines extending from said office to any one of the other offices, means for indicating such line to said operator, signaling paths common to said lines, a signal and a call indicator at the latter office, and means responsive to the seizure of said idle line by said operator for transmitting series of impulses over said signaling paths to operate said signal and said call indicator. 120

- the latter office associated with each operator's position thereat, means responsive to the seizure of said idle line by said outward operator for transmitting a series of impulses over one of said signaling paths for operating one of said signals before an incoming operator's position, and means for transmitting series of impulses over a different path for selecting the call indicator.
- 5 9. In a telephone system, two distant offices, a plurality of transmission lines extending between said offices, signaling paths common to said transmission lines, a signal and a call indicator at one of said offices, a register at the other office for controlling the operation of said call indicator, means for setting said register, means for transmitting a series of impulses over one of said signaling paths for operating said signal, and means for transmitting over a different path other series of impulses in accordance with the setting of said register for operating said call indicator.
- 10 10. In a telephone system, two distant offices, a plurality of transmission lines extending between said offices, signaling paths common to said transmission lines and interconnecting said offices, a signal and a call indicator at one of said offices, means for transmitting a series of impulses over one of said common signaling paths for operating said signal, and means for transmitting series of impulses over a different signaling path for operating said call indicator.
- 15 11. In a telephone system, two distant offices, a plurality of transmission lines extending between said offices, signaling paths common to said transmission lines and interconnecting said offices, a signal and a call indicator at one of said offices, means for transmitting a series of impulses over one common path for initially operating said signal, and means for thereafter transmitting other series of impulses over a different signaling path for operating said call indicator.
- 20 12. In a telephone system, two distant offices, a plurality of transmission lines extending between said offices, signaling paths common to said transmission lines and interconnecting said offices, a signal at each office, a call indicator at one office, means for transmitting series of impulses over one of said common signaling paths for operating said signals, and means for transmitting series of impulses over a different signaling path for operating said call indicator.
- 25 13. In a telephone system, two distant offices, a plurality of transmission lines extending between said offices, signaling paths common to said transmission lines and interconnecting said offices, a signal at each office, a call indicator at one office, means for initially transmitting a series of impulses over one of said signaling paths for operating one of said signals, means for thereafter transmitting series of impulses over a different path for operating said call indicator, and means for then transmitting a series of impulses over the first-named path for operating the signal at the other office.
- 30 14. In a telephone system, two distant offices, a plurality of transmission lines extending between said offices, signaling paths common to said transmission lines, a signal and a call indicator at one of said offices, a register at the other office for controlling the operation of said call indicator, means for setting said register, means for transmitting a series of impulses over one of said signaling paths for operating said signal, and means for transmitting over a different path other series of impulses in accordance with the setting of said register for operating said call indicator.
- 35 15. In a telephone system, two distant offices, a plurality of transmission lines extending between said offices, signaling paths common to said transmission lines, a signal at each of said offices, a register at one office, means for setting said register, a call indicator at the other office, means for transmitting a series of impulses over one of said signaling paths for operating the signal at one of said offices, means for transmitting other series of impulses over a different path to thereafter operate said call indicator in accordance with the setting of said register, and means for causing the transmission of another series of impulses over the first-named path for operating the signal at the first-named office and for restoring said register.
- 40 16. In a telephone system, two distant offices, a plurality of transmission lines extending between said offices, signaling paths common to said transmission lines, a signal and a call indicator at one of said offices, registers at the other office for controlling the operation of said call indicator, means for selecting one of said registers and for associating the same with one of said transmission lines, means for setting said register over said transmission line, means for transmitting a series of impulses over one of said signaling paths for operating said signal, and means for thereafter transmitting over a different path other series of impulses in accordance with the setting of said register for operating said call indicator.
- 45 17. In a telephone system, two distant offices, a plurality of transmission lines extending between said offices, signaling paths common to said transmission lines, a signal at each of said offices, a plurality of registers at one office, means for selecting one of said registers and associating the same with one of said transmission lines, means

- for setting said register over said line, a call indicator at the other office, means for transmitting a series of impulses over one of said signaling paths for operating the signal at one of said offices, means for transmitting other series of impulses over a different path to thereafter operate said call indicator in accordance with the setting of said register, and means for causing the transmission of another series of impulses over the first-named path for operating the signal at the first-named office and for restoring said register.
18. In a telephone system, two distant offices, a plurality of transmission lines extending between said offices, signaling paths common to said transmission lines, a signal and a call indicator at one of said offices, a register at the other office normally disconnected from said signaling paths, means for setting said register, means for transmitting a series of impulses over one of said paths for operating said signal, means operable in response to the operation of said signal for transmitting another series of impulses over said path, and means responsive to the last-named series of impulses for associating said register with a different path whereby series of impulses in accordance with the setting of said register are transmitted over the last-named path to operate said call indicator.
19. In a telephone system, two distant offices, a plurality of transmission lines extending between said offices, signaling paths common to said transmission lines, a signal and a call indicator at one of said offices, a plurality of line registers at the other office, means for selecting one of said line registers, a plurality of link circuits for joining the selected line register to one of said transmission lines, means for preselecting one of said link circuits, a switch operable upon the seizure of one of said transmission lines for completing the connection thereof to the selected line register through said link circuit, means for thereupon setting said line register, means for transmitting a series of impulses over one of said signaling paths for operating said signal, and means for thereafter transmitting other series of impulses in accordance with the setting of said line register to operate said call indicator.
20. In a telephone system, outward and incoming offices, a plurality of transmission lines extending between said offices, signaling paths common to said lines, a signal and a call indicator at said incoming office, a register at said outward office operable to register the number of a wanted line, means for connecting said register to one of said transmission lines, a second register thereupon actuated in accordance with the operation of the first-named register, means for transmitting a series of impulses over one of said signaling paths for operating the signal, and means for transmitting over a different path other series of impulses corresponding to the condition of the second-named register for controlling said call indicator.
21. In a telephone system, outward and incoming offices, a plurality of transmission lines extending between said offices, signaling paths common to said lines, a signal and a call indicator at said incoming office, a cord register at said outward office operable to register the number of a wanted line, a cord circuit for connecting said register to one of said transmission lines, a second register thereupon actuated in accordance with the operation of the first-named register, means for transmitting a series of impulses over one of said signaling paths for operating said signal, and means for transmitting over a different path other series of impulses corresponding to the condition of the second-named register for controlling said call indicator.
22. In a telephone system, outward and incoming offices, a plurality of transmission lines extending between said offices, signaling paths common to said lines, a signal and a call indicator at said incoming office, a plurality of cord circuits at said outward office, a cord register also at said outward office operable to register the number of the wanted line, a line register, means for connecting said line register to one of said transmission lines, a switch common to said cord circuits and operable upon connection of one of them to said transmission lines to transmit the condition existing at the operated cord register through said cord circuits to said line register whereby said condition is recorded thereat, means responsive to the connection of said cord circuits with said transmission lines for transmitting over one of said paths a series of impulses for operating said signal, and means for transmitting over a different path other series of impulses corresponding to the condition of said line register for operating said call indicator.
23. In a telephone system, outward and incoming offices, a plurality of transmission lines extending between said offices, signaling paths common to said lines, a signal and a call indicator at said incoming office, a plurality of cord circuits at said outward office, a cord register also at said outward office operable to register the number of a wanted line, a line register, means for connecting said line register to one of said transmission lines, a switch common to said cord circuits and operable upon connection of one of them to said transmission lines to transmit the condition existing at the operated cord register through said cord circuits.

circuit to said line register whereby said condition is recorded thereat, means responsive to the connection of said cord circuit with said transmission line and operable 5 during the setting of said line register to transmit over one of said signaling paths a series of impulses individual to said transmission line to operate said signal, and means to transmit over a different path 10 other series of impulses in accordance with the setting of said line register after the same has been operated.

24. In a telephone system, distant offices, a plurality of transmission lines interconnecting said offices, a plurality of groups of operators' positions at one of said offices, a plurality of link circuits, an operator's position-finding switch associated with each link circuit and individual to one of said groups of operators, means operable in response to the initiation of a call by an operator in any of said groups for operating, through one of said link circuits, the position-finding switch associated with said link circuit and individual to the group of operators' positions in which the calling operator's position is located to find said position, and means responsive to the finding of said position for selecting an idle one of said transmission lines.

25. In a telephone system, distant offices, a plurality of transmission lines interconnecting said offices, a plurality of groups of operators' positions at one of said offices, a plurality of link circuits, an operator's position-finding switch associated with each link circuit and individual to one of said groups of operators, means operable in response to the initiation of a call by an operator in any of said groups for operating, through one of said link circuits, the position-finding switch associated with said link circuit and individual to the group of operators' positions in which the calling operator's position is located to find said position, and means for thereupon indicating to the calling operator which line has been selected.

26. In a telephone system, distant offices, a plurality of transmission lines interconnecting said offices, a plurality of groups of operator's positions at one of said offices, a plurality of link circuits, means for preselecting one of said link circuits, an operator's position-finding switch associated with each link circuit and individual to one of said groups of operators' positions, means operable in response to the initiation of a call by an operator in any of said groups for operating, through the preselected link circuit, the position-finding switch associated with said link circuit and individual to the group of operators' positions in which the calling operator's position is located to find said position, and means responsive to the find-

ing of said position for selecting an idle one of said transmission lines.

27. In a telephone system, distant offices, a plurality of transmission lines interconnecting said offices, a plurality of groups of operators' positions at one of said offices, a plurality of link circuits, an operator's position-finding switch associated with each link circuit and individual to one of said groups of operators, means operable in response to the initiation of a call by an operator in any of said groups for operating, through one of said link circuits, the position-finding switch associated with said link circuit and individual to the group of operators' positions in which the calling operator's position is located to find said position, and a plurality of switches any one of which is operable in response to the finding of said position to select an idle one of said transmission lines. 70 75 80 85

28. In a telephone system, distant offices, a plurality of transmission lines interconnecting said offices, a plurality of groups of operators' positions at one of said offices, a plurality of link circuits, an operator's position-finding switch associated with each link circuit and individual to one of said groups of operators, means operable in response to the initiation of a call by an operator in any of said groups for operating, through one of said link circuits, the position-finding switch associated with said link circuit and individual to the group of operators' positions in which the calling operator's position is located to find said position, means responsive to the finding of said position for selecting an idle one of said transmission lines, and means operated upon the selection of said line for indicating to the calling operator which line has been selected.

29. In a telephone system, distant offices, a plurality of transmission lines interconnecting said offices, a plurality of groups of operators' positions at one of said offices, a plurality of link circuits, an operator's position-finding switch associated with each link circuit and individual to one of said groups of operators, means operable in response to the initiation of a call by an operator in any of said groups for operating, through one of said link circuits, the position-finding switch associated with said link circuit and individual to the group of operators' positions in which the calling operator's position is located to find said position, a plurality of switches any one of which is operable in response to the finding of said position to select an idle one of said transmission lines, and a number indicator operated upon the selection of said line for indicating to the calling operator the number of the line selected.

30. In a telephone system, distant offices, 130

a plurality of transmission lines interconnecting said offices, a plurality of groups of operators' positions at one of said offices, a plurality of link circuits, an operator's position-finding switch associated with each link circuit and individual to one of said groups of operators, means operable in response to the initiation of a call by an operator in any of said groups for operating, through one of said link circuits, the position-finding switch associated with said link circuit and individual to the group of operators' positions in which the calling operator's position is located to find said position, a plurality of switches any one of which is operable in response to the finding of said position to select an idle one of said transmission lines, a number indicator, and a number indicator controlling mechanism controlled by said line selecting switches and operable upon the selection of a line by any one of them for actuating said number indicator.

31. In a telephone system, an originating office, a terminating office, a line interconnecting said offices, a signaling path, a signal at said terminating office, means responsive to the seizure of said line at said originating office for actuating said signal over said signaling path, a call indicator at said terminating office, a second signaling path, and means controlled from said offices for actuating said call indicator over said second signaling path.

32. In a telephone system, an originating office, a terminating office and a signal thereat, a line interconnecting said office, a signaling path, distributor mechanism associated therewith, means responsive to the seizure of said line for actuating said distributor mechanism whereby the signal at said terminating office is actuated over said signaling path, a call indicator, a second signaling path, distributor mechanism associated therewith, and means for actuating the last mentioned distributor mechanism whereby said call indicator at said terminating office is actuated over said second signaling path.

33. In a telephone system, first and second offices, a line interconnecting said offices, a signal at said second office, a signaling path, means controlled from said first office for actuating said signal over said signaling path, a call indicator at said second office, a second signaling path, a plurality of registers, means controlled from said first office to operate said registers, and means controlled from said second office for effecting the transmission of code impulses from one of said registers over said second signaling path to actuate said call indicator.

34. In a telephone system, a first office, a

second office, a substation, means including a transmission line and a toll switching trunk for connecting said first office with said substation by way of said second office, a signal at said second office, a signaling path, means responsive to the seizure of said line at said first office for actuating said signal at said second office over said signaling path, a call indicator at said second office, a second signaling path, means for actuating said call indicator over said second signaling path to indicate to the operator at the second office the number of the called substation, a signal at said first office, means responsive to the association of said toll switching trunk with said transmission line for actuating the signal at said first office over said first signaling path, a signal at said substation and means controlled at said first office for actuating the signal at said substation over said first signaling path subsequent to the establishment of the connection.

35. In a telephone system distant offices, a plurality of transmission lines interconnecting said office, operators' positions at one of said offices, a cord register at each of said positions, manually operable means for operating said cord registers to record the number of a called line, means individual to said operators' positions for selecting an idle one of said transmission lines, means responsive to the selection of one of said transmission lines for identifying the same to an operator at one of said positions, a line register, a cord circuit, means responsive to the association of said cord circuit with the selected transmission line for associating said line register with said transmission line whereupon the record registered in said cord register is transferred to said line register, a signal individual to the selected transmission line at its terminating end, a signaling path, means responsive to the association of said cord circuit with the selected line for operating said signal over said signaling path, a second signaling path, a call indicator at the distant office, means for transmitting the code of impulses over said second signaling path to operate said call indicator in accordance with the record registered in said line register, and means responsive to the seizure of the selected line at the distant office for transmitting a code of impulses over said first signaling path to actuate the signal at the originating end of said transmission line.

In witness whereof, I hereunto subscribe my name this 12th day of August A. D., 1921.

HUGH D. MACPHERSON.
